UNITED STATES PATENT OFFICE.

JOHN ROYDEN PEIRCE, OF NEW YORK, N. Y.

BOOKKEEPING-MACHINE.

1,219,766.

Specification of Letters Patent. Patented Mar. 20, 1917.

Application filed February 20, 1909. Serial No. 479,189.

To all whom it may concern:

Be it known that I, JOHN ROYDEN PEIRCE, a citizen of the United States, residing in the borough of Manhattan, city, county, and State of New York, have invented certain new and useful Improvements in Bookkeeping-Machines, of which the following is a specification:

In previous applications for patent, particularly Nos. 331,050, of June 9, 1906; 331,757, of August 23, 1906, and 387,868, of August 9, 1907, I have described a system of mechanical bookkeeping in which perforated cards are used to indicate one or more items of a bookkeeping entry, and are adapted to control an apparatus for recording such items upon sheets of a loose-leaf book or the like.

The present application is in part a continuation of the previous applications, and covers certain improvements in the system including the recording machine, the controlling card, and the recording sheet; and covering a number of separately valuable mechanisms. I will first describe in a general way the principal parts and functions of one embodiment of the invention, and then explain the details with reference to the drawings.

The operations are controlled by a small card on which the items to be registered are tabulated by means of perforations. The locations of these perforations determine the record which the machine shall make. Various systems of perforating may be utilized, the simplest being the use of a single hole for each character to be recorded, the particular character being determined by the location of the hole. Preferably, however, a grouping arrangement is employed using for example various combinations of four holes to represent nine digits, the particular digit being determined by the relative positions of the holes and of the imperforate spaces; such a group system resulting in a considerable simplification and reduction in size of the machine. By applying the same principle to perforations grouped in a larger number of spaces a larger number of characters can be provided for, one part of the present machine being arranged to provide for forty characters, including the letters of the alphabet, the Arabic digits, and certain supplementary characters. Besides the perforations indicating the particular characters to be recorded, the card is provided

with other perforations (or equivalent notches, depressions, or similar physical peculiarities) which control the location of the record, as whether it shall be recorded as a debit item or as a credit item upon a ledger sheet. The cards may be varied in color in order to classify them in any desired way. They also contain a number of printed or written items which do not require retabulation.

This card is put in a pocket of the machine and the recording sheet put in another pocket. The pulling of the handle of the machine then makes the desired record. The record may be made by printing or by perforating, or by otherwise marking the recording sheet, different sections of the machine being arranged to print a date, a name or word representing the "distribution", that is, the appropriate bookkeeping account, a number representing the amount in question, and a number representing a continuous balance of all the numbers previously recorded, and by perforating a column in such a way as to represent the same amount as is represented in the balance column. These are the entries which are sufficient for ordinary commercial houses. The machine, however, may be designed to record various other items where it is to be used with special systems of bookkeeping such as in banks, brokerage houses, gas companies, etc.; and a machine which is provided with mechanism for making a number of records may be used for any lesser number by throwing out of operation the desired parts of the machine. For the printing of a continuous balance the machine is controlled by not only the regular controlling card but also by the perforations in the recording sheet representing the last previous balance. This is a very important feature of the invention, although not necessary in all uses to which the invention is to be applied. In the particular machine hereinafter illustrated the new amount to be recorded and which amount is perforated in the controlling card, and the amount of the last balance recorded on the recording sheet, may each be a debit or a credit, and the machine will combine the two numbers by adding them if they are both debit or both credit, and recording the total appropriately as a debit or a credit, or by subtracting the smaller from the larger and recording the difference appropriately as a debit or a

credit. The change from a debit to a credit record is made by changing the color of the printed amount, red ink representing a credit and black ink a debit as is usual in many bookkeeping systems at present. The fact that a perforated balance represents a credit is preferably indicated by a small supplementary perforation. Each time that the machine is operated it shifts the recording sheet a distance of one line, so that in recording all the items for a given day upon a particular account it is only necessary to put in the several appropriate controlling cards one after the other, pulling the handle down and releasing it for each controlling card.

The machine also carries adding wheels which show through a window in the top the total debits and the total credits (or any other desired combination) which have been entered by the machine. These adding wheels are similar in general to those at present employed on listing adding machines, but have a great advantage in being at the top of the machine where they are easily observed. The provision of adding wheels which show always the total debits and the total credits may be availed of in some cases to cut out the mechanism for recording a continuous balance; work which requires only a final balance being easily accomplished by the manual subtraction of the numbers represented by the adding wheels. Or where balances are needed at intervals the necessary manual subtraction may be performed and the adding wheels set back to zero. A listing key is also provided which upon being pressed prevents either of the adding wheels from operating, so that the machine only lists. One set of adding wheels may be allowed to run continuously and the other be set back to zero at intervals, thus securing a grand total and any desired sub-totals.

The recording sheet is ruled according to the character of the business in which it is to be used, and in the particular example hereinafter referred to is the leaf of a loose-leaf ledger provided only with additional columns for the printed and perforated continuous balance, perforated margins to co-operate with the registering and feeding parts of the machine, and a column indicating whether the account in question is a "reverse" account or a "straight" account,—that is to say, whether the record which would be made by the machine under control of the controlling card is to be reversed or not.

The ordinary transactions in the purchase and sale of goods between houses utilizing the present system would be as follows:—The seller would perforate a card which would control a number of operations in the two houses. The perforated card might rep-

resent the total of an itemized memorandum sent with it. It would first control the making in the seller's ledger of two entries, crediting merchandise under the buyer's account and debiting the buyer under merchandise account. He would then send the card to the buyer as a statement or bill with the goods or letter of advice or the like. The buyer would then use the same card to debit merchandise under the seller's account and 70 to credit the seller under merchandise account. He would then sign the card and date it, which would make of it a check for the amount shown on its face. He would then use it to control his bank account by 75 debiting the seller under bank account, and crediting the bank under the seller's account, after which he would return it to the seller as his check in payment of the account. The seller would then use the same card to 80 credit the buyer under bank account and to debit the bank under the buyer's account, after which he would deposit it in his bank for collection. This bank would then use the card in its machine to control the entry 85 of a credit to the seller under clearing house account and a debit against the clearing house under seller's account. The card or check being passed through the clearing house, would go to the buyer's bank, where 90 it would be used to control the entry of a credit for the clearing house under the buyer's account and to debit the buyer under clearing house account. It would then be canceled and returned to the maker like an 95 ordinary check. The amount represented on the card must be entered sometimes on the credit side of the ledger and sometimes on the debit side. It indicates upon its face the name of the buyer, the name of the seller, and the thing bought and sold, but it enters upon the ledger only one of these 100 three items at a time. Under the different merchandise accounts it enters at different times both the names of the buyer and the seller. Under the buyer's account and under the seller's account only merchandise will be entered. The amount of course is also recorded at each operation.

The machine under control of the controlling card and the recording sheet automatically makes the necessary eliminations and the necessary shifting from debit to credit or vice versa. Where such automatic control is not desired, however, the same result may be obtained by means of manually operated keys on the machine, one each for preventing the recording of the name of the thing bought, the name of the buyer, and the name of the seller, and a fourth key for effecting the recording of the amount as a debit or as a credit; even with this system, however, machines which record a continuous balance will preferably show this balance as a debit or credit automatically.

The preferred forms of controlling card
 25 and recording sheets are shown in Figs. 1,
 2 and 3. Modifications thereof are shown in
 Figs. 4 to 11, 42, 47 to 49 and 61.

The preferred form of apparatus, being
 30 that which is controlled by the card of Fig.
 1 and which produces the recording sheets
 of Figs. 2 and 3, is illustrated in the fol-
 lowing figures inclusive: 13 to 27, 31 to 40,
 46, 57, 58, 60 and 63.

Figs. 41, 43, 44 and 45 illustrate a modi-
 35 fied apparatus for making the recording
 sheet of Fig. 42, referred to hereinafter as
 a "single-space sheet."

Figs. 50 to 53^a represent a second modi-
 40 fied form of the machine to adapt it for
 making the gas company ledger sheets of
 Figs. 47, 48 and 49.

Figs. 54 to 56^a illustrate a third modifica-
 45 tion or special attachment which may be
 applied to the preferred form for the pur-
 pose of making out bills directly on the
 machine and for making a "new balance" card
 like Fig. 61.

Figs. 12, 20^b, 20^c and 59 are explanatory
 50 diagrams.

Controlling cards and recording sheets.

Referring to the drawings, and especially
 55 to Figs. 1, 2 and 3, all the controlling cards
 A of one series contain the words "First
 National Bank pay to the order of", or
 equivalent or other desired directions, and
 a pair of perforations B by which they are
 60 to be centered or set in the pocket of the
 machine. The cards are also preferably
 marked with rectangles C in which during
 successive operations there are made per-
 forations D by certain reversing pins in the
 65 machine. These perforations D in turn con-
 trol the subsequent operation of the ma-
 chine. The marked rectangles are simply

for the purpose of indicating at a glance
 whether there is an even or an odd number
 of reversing perforations. The card is per-
 forated once in each operation of the ma-
 chine, the perforations taking place in suc-
 70 cession along a line as shown. Each pair
 of perforations of the card reverses its ef-
 fect upon the machine. In the first and
 second uses of the card it is a "straight" card,
 and the machine records the amount 75
 as a debit or as a credit according to the
 will, so to speak, of the recording sheet.
 In the third operation the first two perfora-
 tions D reverse the previous effect or
 80 tendency. The card is then said to be a 80
 "reverse" card. That is, it causes the ma-
 chine to record as a debit an item which it
 previously caused the machine to record as
 a credit, or vice versa. This is explained
 85 more fully hereinafter. Thus a casual in-
 spection shows whether the card is straight
 or reverse, and at the same time indicates
 whether it has been used twice by the pres-
 ent holder of it, as is necessary in substan-
 tially all double-entry transactions before 90
 forwarding it to the next party.

The card is perforated and printed to
 represent a particular operation or the total
 of a series of items, by a machine combin-
 ing the functions of a typewriter and a per-
 forator, such a machine being illustrated, for
 95 example, in my application No. 396,970,
 above referred to. In the card shown there
 are four sections or columns, the first rep-
 resenting the distribution or name of the
 100 thing bought, merchandise in the present
 case, the second indicating the name of the
 buyer, John Smith, the third indicating the
 name of the seller, John Wanamaker, and
 the fourth indicating the amount of money 105
 in question. Each letter and each digit is
 represented by perforations (by which term
 I include none or one or more) in a vertical
 column under the printed character. Where
 110 letters of the alphabet are to be indicated,
 it is preferable to use a combination of per-
 forations to indicate each character, thus
 effecting a substantial economy of space; the
 numerals being represented by single per-
 115 forations arranged at any one of nine suc-
 cessive points in a column. The numerals
 in this way require nine spaces, and the let-
 ters of the alphabet ten. There may be also
 120 a column for the date, which will be repre-
 sented by figures, as 8-14-08, and is indi-
 cated by the same system of perforations as
 the amount.

The recording sheet E is the merchandise
 account page of the ledger, and indicates as
 usual the date, and the name of the party or
 thing which is debited or credited, accord-
 ing to the color of ink used and the amount;
 these columns being indicated at F, G and
 H respectively, and the debit items being
 indicated on the present drawings by full 130

lines, and the credit items by dotted lines representing red ink. The sheet E contains also columns J at the edges carrying a series of perforations which coöperate with the feeding mechanism of the machine; columns K and L which show in perforations and in print respectively the continuous balance, and a column M which on each line of the record is divided into two spaces, an upper and a lower. Fig. 2 shows in dotted lines in the column K that each horizontal line of the page is wide enough to carry an upper and a lower line of perforations. This is shown only for the column K but the same double space exists in all the columns. The upper space in each line in the column M is for receiving a perforation which controls the machine in such a way as to reverse the operation which would otherwise take place under control of the controlling card. Where such perforations N occur upon a sheet it is called a "reverse" sheet; where they do not occur, a "straight" sheet. Ordinarily a sheet showing any particular account will be straight throughout its length, or will be reverse throughout its length. Before the card is put in the machine, however, the perforation N is provided only in the uppermost line. The machine will make corresponding perforations for the succeeding lines as each item is recorded. The perforations N in the upper space of each line control the color of the entry in the columns F, G and H.

The perforations O in the lower spaces, on the other hand, control the record in the continuous balance columns K and L. It will be understood that if the account commences with a series of debit items the balance will show a continuously increasing debit. If then a credit item follows of larger amount than the total debits, the balance must show a credit. The inking ribbon of the balance column L must shift from black to red, and the machine must subtract the total debits from the credit and must continue to subtract debit items during succeeding operations until the balance is again reversed. In some cases it must subtract the last item from the previous balance, and in other cases subtract the previous balance from the last item. The balance perforations O are made by the machine for the purpose of controlling these several shifts, and they are made continuously in successive lines so long as the net balance is a credit. Such a perforation thus indicates a reversal of the usual operation. If there is no such perforation and the previous balance is a debit, then the next single amount will be, algebraically speaking, added (being considered plus or minus as it is a debit or credit respectively). If, however, a perforation O exists in the previous line, showing that the previous balance is a

credit, then the next single amount will be subtracted, and this reversal of the usual operation will continue as long as the last previous balance is a credit item.

The sheet P of Fig. 3 is originally the same, that is, ruled in the same way, as the sheet E of Fig. 2. It is supposed to be the page showing the account of John Smith, the buyer, in the ledger of John Wanamaker, the seller. It will ordinarily show a series of debit items, and will be a straight recording sheet. The balance columns, however, will be reversed whenever a credit balance is shown, and corresponding balance perforations O will be made by the machine.

Systems of perforations.—The successive numeral digits are represented on the controlling card (Fig. 1) each by a single space, preferably in a vertical column as above stated. A perforation in the uppermost space represents 1, and the next space 2, etc., down to 9, the numeral 0 being represented by the absence of any perforations.

For letters of the alphabet a more complicated system is advisable as economizing space. I have provided for representing in a single column any one of a series of 40 characters, including the regular letters, various typographical signs, figures, etc. This system is used in each of the three columns headed "Merchandise", "John Smith", and "John Wanamaker" respectively in Fig. 1, and which may be called the listing columns. Ten spaces are allotted to each character, preferably in a vertical line, and the series of characters is divided into five sections. By the presence of a perforation in any one (or in none at all) of the four lowermost spaces, the particular section or group of the series of characters is indicated, and by the presence of a perforation in any one of the remaining nine or ten spaces of the column the particular character in the selected section is indicated.

The digits in the balance column K of the recording sheet are indicated by perforations (or the absence of perforations) in four spaces arranged in a square. For example, in the uppermost line (Fig. 2) I have dotted in the outlines of the imaginary squares containing the four spaces. In the six squares shown the combinations of perforations represent the six figures printed at the right. It will be clear on consideration that in the four spaces in question there can be nine different combinations, any one of which may be selected to represent any desired digit; but these are preferably arranged in a certain order for convenience in the machine, as hereinafter described more fully.

An indication of the system of perforations and the numbers represented by different groupings of the perforations, is seen in

Fig. 20^b, the numerals represented being indicated alternately at the right and left of the figure. For convenience in designating the spaces in each square, they are numbered as in the diagram, Fig. 20^c, No. 1 the lower right-hand corner, No. 2 the upper right-hand, No. 3 the lower left-hand, and No. 4 the upper left-hand. Zero is represented by no perforations; one by a perforation in the space No. 3; two by perforations in spaces Nos. 4 and 3; three by a perforation in space No. 4; four by perforations in spaces Nos. 3 and 1; five by perforations in spaces Nos. 1, 2, 3 and 4, and 10 the remaining figures by reversals in a symmetrical arrangement of figures 5 to 0. This system has a great advantage in compactness and also in the faculty of shifting the mechanism from its position for the punching of one number to its position for the punching of the next number, by a movement only half as long as the space occupied by a set of perforations. For example, the squares in which the four perforating spaces lie may be one-fourth of an inch long, and the machine may shift from positions corresponding to adjacent numbers by a movement of only one-eighth of an inch; the mechanism for perforating in the lower two spaces (Nos. 1 and 3) of any square being used for printing in the upper two spaces (Nos. 2 and 4) of the next square. This system, it will be seen, is on the same principle as the alphabet system above described, a perforation in a certain space being common to a group of characters so as to determine the selecting of such group; and a second perforation or other perforations serving, when found in combination with the first, to determine the selecting of a particular character of said group. Thus, referring to Figs. 20^b and 20^c, a perforation in space No. 1 is common to the group of four figures, 4, 5, 7 and 8, and determines or selects this group. Where this No. 1 perforation occurs in combination with three blank spaces, the individual character 7 of the group is selected. Where the No. 1 perforation occurs in combination with a No. 2 perforation the individual character 8 of the group is selected. Where the No. 1 perforation occurs in combination with a No. 3 perforation the individual character 4 is selected. And where it occurs with perforations Nos. 2, 3 and 4, the individual character 5 is selected.

Use of the card.

Fig. 12 indicates the various uses to which a single card may be put in the ordinary course of business, say between a wholesale and a retail house. The card is used separately twelve times. The order in which the entries are made by means of the card is indicated by the numbers in parentheses

in the diagram and on the card (Fig. 1), numbers 1, 2, 7 and 8 being in the books of the creditor or seller; numbers 3, 4, 5 and 6 being in the books of the debtor or buyer; numbers 9 and 10 in the creditor's bank, 70 and numbers 11 and 12 in the debtor's bank. The operations in the clearing house are not indicated, but they may be various. The condition of the card, whether straight or reverse, is indicated by the letters "S" and 75 "R" in parentheses in Fig. 1. The card starts as a straight card. In the first operation the first perforation D in the bottom of the card is made, and in the second operation the second perforation D, and this 80 reverses the card. When it was a straight card it made a debit entry (supposing the entry unaffected by the recording sheet); when it is a reverse card it makes a credit entry. For the third and fourth operations 85 therefore,—that is to say, while either two or three of the perforations D appear, it makes a reverse or credit entry in the ledger (that is, it tends to do so, and will do so unless there be mechanism controlled by the 90 ledger sheet for reversing the card). The diagram shows that after each pair of operations the card is reversed. The first rectangle on the card containing the first pair of perforations D indicates therefore that 95 the card has become a reverse card. When, in addition, the two perforations in the second rectangle appear, the card is a straight card again. Where only one perforation D appears in a rectangle, it is ignored, the rectangle first completely perforated indicating the nature of the card, whether straight or reverse. With this knowledge the operator may manually shift the mechanism to reverse the effect of the card in making a 100 record (that is, to make a credit record with a straight card, or a debit record with a reverse card); or (and preferably) the ledger sheet is provided with one or more perforations N or equivalent physical peculiarities which control the machine and automatically cause or fail to cause a reversal of the natural effect of the card. For example, the perforations N of the reverse ledger sheet E of Fig. 2 cause a reversal of 11 the effect of the card, so that if it be a straight card it will print a credit, and if it be a reverse card it will print a debit. The sheet P of Fig. 3, however, is a straight ledger sheet and will not ordinarily affect 12 the indentation, so to speak, of the card. The perforations O relate not to the entries which are controlled directly by the card, but to the balance entries which are directly controlled by the adding and subtracting 12 mechanism of the machine.

The machine (in general).

The machine Fig. 13 is actuated by introducing a controlling card in the front pocket 13

Q, and a record sheet in the rear pocket R, pushing each down as far as it will go, and then turning the operating shaft S by pulling forward the hand lever T and then releasing the same, which is carried back by suitable springs. This movement of the shaft causes all of the selecting, punching and printing operations above referred to, releases the controlling card, and advances the recording sheet one line. The parts of the machine are supported principally upon front uprights U and U' Figs. 14, 15 and 17 embracing the pins which communicate the various matters on the card to the recording sheet, and between the front edges of which the pocket Q is extended, and rear uprights V and V' which embrace the rear pocket R and the mechanism for transmitting to the sheet therein not only the matters of information on the card, but also the matters of information in the balance mechanism of the machine. These fixed uprights or side frames are attached to the base of the machine, and are preferably tied to each other near their upper portions by a tie rod g at the right, and a similar rod g' at the left.

Referring to Fig. 17, it may be said roughly that the mechanism within the portion W of the width of the machine is the date mechanism; the mechanism within the portion X is the name-printing or listing mechanism; that within the portion Y the amount mechanism; that within the portion Z the balance perforating mechanism; and that within the portion a the balance-printing mechanism. The punches for making the feed holes in the columns J (Fig. 2) at the sides of the sheet are indicated at opposite sides of the rear pocket at b and b'. The punches for making holes in the column M of the recording sheet are indicated at c and c' (Figs. 17, 21 and 33), one being above another for making the amount-reversing or card-reversing holes N, whereas the lower punch is for making the balance-reversing holes O. Referring back to Fig. 17 punches d for making the balance perforations are arranged in pairs in plan, being in groups of four, one pair above another, as previously explained. The types e for printing the date, the name, the amount, and the balance, are substantially alike. The handle T for operating the main shaft is arranged at the right-hand side of the machine, and the backward movement of the shaft is braked by a dash-pot f (Fig. 15) connected at its lower end to a crank on the left-hand end of the shaft and having its piston rod projecting from its upper end and connected to the cross-bar g' between the two side frames U' and V' of the machine.

The date, listing, and amount mechanisms have as motion-transmitting mechanism various sectors mounted upon a main shaft

h, the center line only of which is indicated fully in Fig. 17, and which extends across substantially the width of all the mechanisms, its ends being mounted in frames j at the right and j' at the left of the machine (Figs. 14, 15 and 25) which carry a number of subsidiary mechanisms and which are, roughly, mushroom shaped. These movable mushroom frames j and j' are pivoted at their lower ends upon the operating shaft S, and are adapted to first stand in the forward position with the shaft h and the segments carried thereby toward the card-pocket to take off the reading on the card, and to then swing backward toward the recording sheet to enter thereon the record taken from the controlling card. The rearward movement must be under substantial pressure because of the number of perforations which are made thereby. The movement is preferably effected by means of toggle links k l connected to the forward fixed frame U and to the movable frame j respectively, and pivotally connected to each other and to a link m which is provided near its lower end with a pin n lying in a cam-groove o of a cam p which is mounted on the operating shaft S; so that the turning of the shaft S from the position of Fig. 14 to that of Fig. 25 pulls down the link m and straightens the toggle and throws the movable frame j over toward the recording sheet. The mechanism is duplicated at opposite sides of the machine. The first portion of the cam slot o is concentric with the shaft, so that the movement of the movable frames j and j' does not take place until after time has been allowed for the setting of the mechanism to positions corresponding with the perforations in the card.

The card pocket Q may be divided by a partition, as shown in Fig. 17 between the parts W and X, into two spaces, one for a date card and the other for the card controlling the other matters to be recorded, where a separate date card is always to be used in the machine.

The shaft S is retracted by a spring S' in the bottom of the machine and limited in its backward movement by a heavy bar S² as shown in Figs. 19 and 20.

Type carriers and related mechanism.

The type-carriers are sector-shaped members pivoted upon the shaft h. In Fig. 17 the date sectors, that is to say, the sectors within the space W and carrying the type which print the date, are indicated at g, the sectors within the space X and carrying the alphabet or listing type at r, the sectors within the space Y and for carrying the type for printing the amount at s, and the sectors within the space a and carrying the type for printing the balance at t. The date sectors and the amount sectors within the space a

and work on identical principles, and these sectors are illustrated in side elevation at *s* in Figs. 19 and 27. The listing or alphabet sectors *r* are indicated in side elevation in Figs. 18 and 26. The balance sector *t* is shown in Fig. 22.

Each of these sectors carries a rim with a number of types therein, so that as the sector swings upward about the shaft *h* the successive types come into printing position. When in this position they are struck by a hammer *u*, the mechanism for operating which is of well-known types or may be of any suitable type such as those in the Burroughs or Wales adding machines.

For printing black and red to represent debits and credits, a pair of correspondingly colored typewriter ribbons is used, or (preferably, and as shown) a single ribbon colored partly red and partly black in longitudinally divided halves, and wound on spools *v v'*. (Figs. 16, 17 and 63.) There are two ribbons, one for the date, listing and amount mechanisms and the other for the balance mechanism. The ribbon for the first mechanisms may be traced from the spool *v* by way of the portions *w, w', w², w³* and *w⁴*, to the opposite spool *v'*. The positions of the spools *v v'* are indicated in Fig. 16, in dotted lines in order to avoid obscuring the figure. In the same figure I have also shown in dotted lines a pair of spools *x* and *x'* which carry the ends of the ribbon for the balance printing, the path of this ribbon being indicated in Fig. 17 at *y, y'* and *y²*.

The portion *w²* of the ribbon is guided at its ends in guides *z* (Figs. 18, 19 and 63) which are supported on uprights 21 which move vertically in guides 22, the lower ends 40 of said uprights being pivoted upon arms 23 on a shaft 24 which is rocked by the debit and credit mechanism so as to shift the ribbon up or down to bring the red or black portion thereof into play. This debit and credit mechanism is referred to more in detail hereinafter.

Controlling pins.

The positions to which the sectors move, and consequently the characters, letters or figures, which are printed, depend upon certain controlling pins which pass through the holes in the controlling card. Such pins are indicated at 24, in Figs. 17, 18, 19, 26 and 27, and are arranged in rows and columns corresponding to the spaces upon the card which may be punched. They are used, as will appear from Fig. 17, only for the dating, listing, and amount sections of the machine, but not for the balance section, since the latter is not controlled directly by the card. These pins are guided at their forward ends by correspondingly located openings in the walls of the pocket, and at their rear ends in a plate 25 extending across the

rear of the bank of pins and fixed to the side frames *U* and *U'* as indicated in Fig. 17. The pins are pressed toward the card in the pocket by the forward movement of a plate 26, which is apertured for the passage of the several pins, and which is moved forward against springs surrounding the pins and bearing against collars near the forward ends of the pins; the backward movement of the plate 26 serving to retract the pins by engaging the larger shouldered rear portions thereof.

The forward movement of the plate 26 is effected by its connection at its two ends (Fig. 17) to forwardly and backwardly reciprocating plates 27 which are connected to the upper ends of levers 28 (Figs. 14 and 15) which are pivoted upon a cross-shaft 29, the lower ends of these levers being connected by links 30, angle levers 31 pivoted upon the mushroom frame *j*, links 32, and arms 33, to a shaft 34 running through the upper part of the mushroom frame, and actuated when the pins are pressed forward, and controlling the adding wheels as hereinafter described.

Mechanism controlled by controlling pins.

The controlling pins 24 when they are moved forward limit the movement which may be made (when the hand lever is pulled) by the type-carrying sectors, preferably through the intermediation of other sectors, as hereinafter described. When there is no perforation in any column of the card the type-carrying sectors will not move. They stand normally with the zero one space below the printing line. For the purpose of causing the operation of the zero a supplementary stop is used, limiting the movement of the type-carrying sector to one step, this stop being withdrawn when any one of the pins 24 is advanced. This supplementary stop or zero stop is indicated in Figs. 18, 19 and 20 as a hook 35 which is connected by a spring 36 to an arm 37 of a lever which has another arm 38 lying in front of a series of pins 39 carried at the sides of the rear portions of the controlling pins 24. The lever arm 38 is provided also with a pin 40 working in a slot in a link 41 which connects the hook 35 to the spring 36. The arm 37 of the lever is connected by a spring 42 to one of the side frames so as to give to the arm 38 a rearward movement which withdraws the controlling pins from the card. The hook or stop 35 limits the movement of an arm 43 which in turn controls the movement of the type-carrying sector. When however the stop 35 has been withdrawn and the member 43 has been operated, with a downward movement, then upon the return movement of the handle the plate 26 in its rearward movement puts the spring 42 under tension, bringing the 1

pin 40 in engagement with the link 41 to press the stop 35 against the member 43 so that as soon as the latter is restored to its original position the stop 35 springs into the operative position shown in Figs. 18 and 19.

The above described zero stop is controlled by the pins regardless of whether they are moved singly or in combination.

- 10 The movement of the printing sectors however depends upon (in the case of printing only figures) which pin passes through the card, and in the case of the listing or alphabet-printing sectors upon the particular combination of pins which passes through the card. It is well therefore to understand the pins and their arrangement as used for the alphabet before proceeding further with the description of mechanism.
- 15 This is illustrated most clearly in Fig. 18.

The member 43 is given a downward impulse under the pull of a spring when the handle of the machine is operated, and the extent of this downward movement is determined by the controlling pins, and in turn controls the extent of movement of the type-carrying sector. The pins exert a double influence upon the type-carrying sector, first by controlling the extent of

- 30 movement of the member 43, and second by controlling the extent of movement which the type-carrying sector shall have over and above the movement of the member 43. In the alphabet or listing mechanism of Figs.

- 35 18 and 26, for example, the type-carrying sector *r* has an arm 44 extending in the opposite direction beyond the shaft *h* and which is provided at its outer approximately circular edge with a series of undercut shoulders 45, which shoulders by the engagement of one or another with an arm 46 pivoted on the member 43 determine the position of the type-carrying sector relatively to the member 43, and determine which of
- 40 45 the five groups into which the characters carried by the sector are divided shall come into play.

The control of this group or section selecting mechanism is effected as explained above, by the perforating of none or of any particular one of the lower four spaces in any column on the card. The controlling pins corresponding with these four spaces are provided with supplementary laterally projecting pins 47 which are adapted to engage an arm 48 which is pivoted at its lower end upon the member 43, is pressed toward the rear by a spring 49, (which is attached at its upper end to member 43 and at its lower end to a lateral projection of the member 48), and is connected with the arm 46 by means of a spring 50. The reason for separating the members 46 and 48 will appear later. For the present they may be regarded as two parts of one member moving always

together. The lower four pins move each a different distance, as will appear from the stops near their forward ends. The advanced position of one of them is indicated in Fig. 26. Consequently the pins or projections 47 of the different control pins travel different distances; the lowermost one traveling four spaces, the next three spaces, the next two, and the next only the usual one. Consequently the arm 48 which is engaged by the projection 47 receives from the uppermost of the lower four pins a single-step forward movement, from the next a double step, from the third a three-step, and from the fourth a four-step movement; and the arm 46 is moved accordingly, its forward movement being limited by the portion 51 of the arm 48. The upper end of the arm 46 will therefore move forward into the path of movement of the second, third, fourth, or fifth of the shoulders 45 on the extension 44 of the type-carrying sector, and will correspondingly limit the downward movement of the arm 44 and the upward movement of the sector relatively to the member 43.

The type-carrying sector is ordinarily in the position of Fig. 18 prevented from moving upward, and its opposite arm 44 from moving downward, by means of a rod 52 extending across the under edges of the entire group of arms 44, so as to hold all the sectors down; staggered springs 53 53^a (Figs. 16, 18 and 26) being provided for pulling them down as soon as the rod 52 is released. The rod 52 is mounted in arms 62 (Fig. 17) 100 on the oscillating shaft *h*.

The member 43 is normally held up by a spring 54 pulling down upon an arm of the same member at the opposite side of the shaft *h*, and is pressed downward by the engagement of the member 44 with the arm 46 which is pivoted on the member 43. The spring 54 serves to insure that the arm 44 which determines the selection of the group of characters shall move to engagement with the arm 46 before the arm 43 which selects the individual character. The controlling pins determine the limit of the downward movement of the member 43, which in turn limits the final downward movement of the member 44 and the final upward movement of the sector. For this purpose all the controlling pins of a column are provided at their rear ends with lateral pins or projections 55, which when the pins are moved forward move into the path of a shoulder 56 on the member 43, and limit its advance movement. It will be observed that the group or section-controlling pins, the last four of the column, are provided with lateral pins 59 which serve as individual selecting pins and also with group selecting pins 47 (see Fig. 18). This capability of operation makes possible the selecting of a great number of characters with comparatively few 130

pins, and permits the use of a very compact card. For example, the mechanism illustrated carries forty characters, which may be the letters of the alphabet, the Arabic numerals, and some arbitrary symbols, such as "&," and punctuation marks.

Where, however, a smaller number of characters is sufficient for the work desired, as in printing dates, journal numbers, or amounts where numerals can be used alone (Figs. 19 and 27), the group- or section-selecting mechanism is unnecessary. Nine selecting pins 24 are sufficient, zero being indicated by the absence of any perforation in the card, and consequently by the failure of all the pins to enter the card. The movement is transmitted to the sectors *s* carrying the type by arms 56^a at the forward side of the shaft *h* and which are provided with staggered springs 57^b and 57^c tending to advance these arms downward, their movement being normally (Fig. 19) arrested by the rod 52 previously referred to, which holds all the sectors in their retracted positions, and which when released allows an advance movement and when thrown back to its original position restores them all to their starting positions. The movement of the member 43 of the amount-printing mechanism is limited by lateral pins or projections 55 on the rear ends of the pins engaging a shoulder 56 as in the listing mechanism just described. The member 43 carries in this case a pivoted member 58 the upper edge of which constitutes a cam which is pressed toward a fixed roller or pin 59 mounted on the frame of the machine by means of a spring 60, and which consequently swings forward gradually as the member 43 carrying the cam 58 advances downward. The arm 56^a of the type-carrying sector is provided with a number of shoulders 61 adapted to engage the end of the cam 58 in the successive outward positions to which the latter swings as the member 43 carrying such cam swings downward one, two, or more steps. In Fig. 27 the third of the controlling pins is advanced and the member 43 is advanced three steps, and the cam 58 is swung forward sufficiently to engage the third of the steps 61 which limit the advance movement of the type-carrying sector.

The mechanism for determining the movement of the type carrier or other record-making or record-controlling member by the movement of the pins into holes in the card in various combinations is claimed broadly in my application No. 601,817, filed January 10, 1911; the present application including only claims to said mechanism as distinguished from the mechanism of said application No. 601,817.

The rod 52 which prevents the advance of the sectors above described is carried on the end of arms 62 (Fig. 17) on the shaft *h* and

which arms are oscillated by said shaft. The oscillation of the shaft *h* is effected in the manner shown in Figs. 14 and 25. When the operating shaft *S* is turned forward the roller 63 carried by the cam *p* travels along the edge of a member 64 which is guided by a slot 65 embracing a pin or roller 66 carried by the movable frame *j*; the upper end of the member 64 being connected to an arm 67 on the shaft *h*. This mechanism is provided at both sides of the machine so as to operate the shaft *h* from both ends. The arm 67 at each side is normally held up by a stop 68 engaging under its end, suspended from the upper part of the movable frame *j*, and connected by a link 69 with an arm 70 upon a shaft 108 which controls the "no-card" lock, that is to say, the lock which holds the machine so that it shall not operate unless a card is placed therein. This "no card" locking mechanism is shown on the shaft 108 in Fig. 18 and is described hereinafter. The placing of a card in the pocket permits the forward movement of the arms 70 on the locking shaft, and a consequent withdrawal of the stops 68. Thereupon the forward movement of the operating shaft and of the rollers 63 releases the members 64 and allows them to move downward at the desired rate and allows the arms 67 to swing down and with them the shaft *h* and the rod 52 which normally prevents the advance of the sectors. The springs within the machine then pull down the forward arms which carry upward the sectors at the rear, until these forward arms are stopped by the controlling pins in the manner previously described.

Upon the further movement of the operating shaft *S* and the downward movement of the toggle-operating link *m*, the lower end of this link, which is forked over a pin or roller 72 on an arm 73, (Fig. 14) causes a downward movement of said arm and a rotation on its shaft 74 which shaft extends within the machine, as shown in Figs. 18 and 19, and carries hooks 75 which hold the followers 76 until the latter are to be released, when, under the influence of their springs 77, they swing upward about their pivotal points 78, the projections 79 carried thereby engaging the rear edges of the members carrying the hammers *U*. Attached to the shafts 78 upon which the followers 76 are pivoted are arms 80 carrying a cross-rod 81 which is pressed downward to restore the followers to engagement with the hooks 75 and which is lifted or released to permit the operation of the followers when the hooks 75 (and in some cases other controlling members in addition) are withdrawn.

The shaft 78 is shown in Figs. 14 and 15 projecting through the opposite movable frames *j* *j'*, and provided with arms 82 which at their forward ends carry links 83

the lower ends of which run in cam-grooves 84 and are guided by links 84^a so that they are lifted as the operating shaft is turned forward, and thus release the followers 5 which operate the hammers.

The followers 76 which control the hammers of the listing or alphabet mechanism of Fig. 18 are provided with supplementary locks in addition to the hook 75 which locks 10 the entire group of followers, and whose withdrawal releases them all; these supplementary locks being most clearly shown in Fig. 31 and being preferably in the form of hooks 85, 85^a, and 85^b, pivoted upon the 15 fixed shaft 86 and drawn backward by springs 87, and pressed forward by rods 88, 88^a, and 88^b respectively on the ends of levers 89, 89^a, and 89^b which are pivoted on the shaft 86, and the rear ends of which are 20 connected by links 90, 90^a, and 90^b with arms 91, 91^a, and 91^b, on a shaft 92 extending from right to left at the back of the machine or on a sleeve on said shaft.

Fig. 31 shows these parts in perspective, 25 showing a reduced number of hooks in each group for the sake of clearness, and showing the hooks widely separated from each other. The hooks 85 and 85^a control respectively the second and first names of parties, 30 and the hooks 85^b control the distribution. In addition to the separate control of the hooks 85 and the hooks 85^a respectively, there is a common control of both these sets of hooks by a rod 88^c carried in the forward 35 ends of levers 89^c mounted likewise on the shaft 86 and having rear ends which are connected by links 90^c with arms 91^c on the shaft 92. The arms 91^b and 91^c which effect the locking either of both the parties or of 40 the distribution alternatively are fixed on the shaft 92 so that the rocking of this shaft actuates one or the other of the corresponding sets of hooks. We may call these the main sets of supplementary hooks. A forward 45 movement (in the direction of the hands of a clock) of the shaft 92 throws upward the links 90^c to release the hooks 85 and 85^a, and throws downward the links 90^b to hold the hooks 85^b in their engaging 50 positions. The releasing of one or the other of these main sets to determine the printing of either the distribution, on the one hand, or the name of one of the parties, on the other hand, is a matter which is controlled 55 by the ledger sheet, and the shaft 92 carries a depending arm 97 connected to a link 98 (Figs. 31 and 33) extending from front to back along the bottom of the machine, and having a lever 98^a extending upward from 60 its rear end by means of which the link 98 is moved forward or backward under control of the upper perforations N in the recording sheet.

The supplementary hooks 85 and 85^a 65 constitute what may be called secondary sets,

one set being actuated alternatively with respect to the other according as the controlling card is a straight card or a reverse card. For this purpose the rods 88 and 88^a are connected by their links 90 and 90^a respectively, and their arms 91 and 91^a respectively to a sleeve 92 which is loose on the shaft 92, said sleeve being actuated by a depending arm 93 connected with a link 94 (Figs. 31 and 18) which runs toward the 75 front of the machine and is connected with the lower end of an arm 95 depending from a shaft 96 extending between the forward side frames U and U', and which is controlled by the straight and reverse perforations D of the controlling card in a manner hereinafter explained. When the link 94 is shifted toward the back of the machine the hooks 85 covering the seller's name are held in engagement and the hooks 85^a are released; and when the link 84 is drawn toward the front of the machine the reverse 80 operation takes place.

The shaft 92 at the rear of the machine determines whether the distribution item or 90 one of the names on the card shall be printed on the sheet. (Compare Figs. 2 and 3.) With a reverse ledger sheet the listing or alphabet mechanism is suppressed to such an extent as to print only the name of one of 95 the parties. In printing on a straight ledger sheet the listing mechanism is suppressed except as to the column for indicating the goods. The suppression of any portion of the matter is effected by simply restraining 100 the hammers for the corresponding section or group of type-carrying sectors.

The lever 98^a extends upward in the rear of the pocket as shown best in Figs. 21 and 33, being pivoted on a shaft 98^b and carrying at its upper end a feeling pin 98^c adapted to enter an upper hole N of a reverse ledger sheet. A spring 98^d tends to pull the link 98 backward to cause the entrance of the feeling pin into such hole in the sheet. 105 Consequently when such a hole N exists the link 98 is moved to the rear with the effect above stated. The link 98 at its forward end is connected to the debit and credit mechanism. 110

Debit and credit mechanism.

The connection of the link 98 with the debit and credit mechanism at the front of the machine is by means of an angle lever 120 99 (Figs. 19, 21 and 33) and an upright link 100.

The connection of the card-controlled link 94 above referred to (Fig. 18) with the debit and credit mechanism is by way of the arm 125 95 and shaft 96, as previously described, and thence by an arm 117 (Fig. 19) on the shaft 96 and a link 118 running to the forward part of the machine.

The lower set of perforations O in the re- 130

cording sheets and which determine whether the balance is a straight or reverse balance also act on the debit and credit mechanism. The control is similar to that of the straight and reverse perforations N in the ledger sheet; that is to say, there is a pin 98^a in the rear of the recording sheet (Figs. 15 and 21) pocket and just below the pin 98^a and which is connected by a lever 98^b similar to 98^a, and a link 98^c similar to 98, which link is drawn backward by a spring and causes the pin 98^a to move forward, whenever there is a balance-reversing perforation in the recording sheet. The link 98^c is connected at its forward end through an angle lever 99^a to a vertical rod 100^a similar to the rod 100. The debit and credit mechanism is therefore controlled by the vertical link 100 coming from the reverse-ledger perforations, the reverse link 100^a coming from the balance-reversing perforations, and certain feelers 101 and 102 (Fig. 21) entering the straight and reverse perforations D of the controlling card. Fig. 32 shows the interconnection of these parts, the parts being shown with an exaggerated lateral separation for clearness. Figs. 21, 21^a, 33, 34 and 46 should also be referred to in this connection.

The debit and credit mechanism in turn controls the indicating or indicating and billing dials or wheels hereinafter referred to, the mechanism for changing from addition to subtraction in computing the balance, the mechanism for making reverse perforations in the sheet, the ribbon-shifting mechanism, the hammer suppressing or selecting devices of the listing mechanism, and other parts connected with these.

The machine is provided with feelers corresponding in position to the spaces for the perforations D in the card, these feelers being indicated at 101, each of the feelers being surrounded by a punch 102 for making one of the large perforations D in the card. The feelers 101 are arranged in six pairs. Calling the effect of the card in its first operation the straight effect, the passage of the first pair of feelers or pins 101 through the card (in the first and second operations) will cause it to have a reverse effect upon the mechanism. In the fifth use of the card the passage of the second pair as well as the first pair of pins 101 through the card will bring its effect back to the original straight effect. The passage of the third pair of pins will again reverse the effect, etc. The passage of any one pin insures the actuation of the surrounding punch 102 of the next pin so as to make the next perforation. The pins 101 are normally pressed forward by springs 102^a reacting against a cross-bar which supports their rear ends. They are held back by arms 103 against which they bear, each of said arms being alongside of a member 104 pivoted upon a

shaft 104^a carried by the arms 103^a of the cross-plate 26 which advances the main controlling pins, at a point just below the pins 101, so that when said plate 26 is advanced to advance the controlling pins it advances 70 also the pivoted member 104. A comb or perforated plate 103^a (Fig. 21) connected to the lower part of the plate 26 embraces collars at the rear ends of the punches 102 to withdraw the latter and also the pins 75 101 when the plate 26 is moved backward. After a pin 101 finds an opening and passes through the card, the member 104 corresponding to the following space upon the card is lifted so that its end engages behind the rear end of the corresponding following punch 102, and the continued movement of the plate 26 effects the punching of the hole in the card. To effect this, the pin in passing through the card effects a forward movement of the arm 103 of one space and causes a slot 105 therein to ride upon a pin 106 carried upon an arm 107 (on a fixed shaft 107^a) belonging to the next higher space, thus lifting said pin and with it the 80 arm 107 which underlies the arm 104 whose end is to be lifted to a position in the rear of the punch to push the latter forward.

All the arms 103 are pivoted upon a common shaft 108. Between the second and 95 third and the third and fourth of the members 103 there are provided kickers 109 (Figs. 32 and 46). These kickers, however, are omitted from the next two spaces, reinserted in the next two, etc. Each kicker 100 is pivoted upon the succeeding member 103, and has at its upper end a fork engaged by a pin on the preceding member 103, so that when the preceding member 103 of a pair is advanced and the succeeding member not 105 advanced the intermediate kicker has its lower end swung backward to operative position. This action takes place on the third use of the card when the first two perforations D are found in the card, the second 110 member 103 actuating the kicker which is pivoted on the third member. At the next operation (the fourth use of the card) the second and third members 103 both move forward, and the intermediate kicker is not 111 actuated, but the kicker between the moved third member 103 and the unmoved fourth member is actuated. On the next operation the second, third, and fourth members 103 all move forward and there is no kicker 120 actuated. Thus a kicker is made operative upon the third and fourth uses of the card, suppressed upon the fifth and sixth uses, and so on alternately. The lower ends of the kickers strike the shaft 110 (suspended from 125 swinging arms on a shaft having its ends supported in the frame of the machine) upon which are pivoted links 111 which are connected to an arm 112 upon a sector 113 pivoted upon a rod 114 running along the 13

front of the machine, and having flanged portions 115 and 116 above, and below an unflanged space.

When the pin 101 advances, it effects an advance of the next punch 102, but it is desirable to restrain the next pin 101 passing through said punch. This restraint is insured by a locking pin 101^a on an arm 101^b which is pressed upward by a spring 101^c and which rises with the arm 107 of the previous group, so that the pin 101^a enters a notch in the arm 103 which controls the movement of the next feeling pin 101, and thus prevents movement of said pin. The pin 101^a is retracted by the downward movement of the arm 107 striking said pin and pressing it down out of the notch in the arm 103.

As described above, the shaft 96 controls the releasing of one or another of the names of parties on the card, by controlling the release of the hammers of the debtor's section or of the creditor's section. The sector 113 just described, with its flanges 115 and 116, is for determining the movement of the shaft 96. For this purpose the shaft 96 is provided with an arm 117 at the end of which is a link 118 which endeavors to move forward when the pin-advancing plate 26 is manipulated, the end of the link 118 striking against one of the flanges 115 or 116 and being practically immovable so as to hold one set of hammers locked and the other released; or passing through the unflanged space and shifting the mechanism so as to release one of the sets of hammers and hold the other set. In what we may call the straight position the segment 113 is in its middle position. In order to secure the reversal of the operation it is necessary that the proper feelers 101 should find and pass through a proper pair of openings D in the card, and should kick a link 111 backward and throw the sector 113 downward so as to bring the flange 115 into the operative position. The card therefore effects a reversal of the normal position of the sector 113 by moving it downward. The link 118 is given a forward impulse through a spring 118^a engaging a collar on the link, and which spring is engaged at its rear end by a depending portion of the plate 26, so that as the plate advances the spring is compressed and tends to move the link forward.

The question whether the name of the goods or of one of the parties is to be printed is as stated above determined by the nature of the recording sheet as a reverse or a straight sheet having perforations N or lacking such perforations; and the consequent movement is transmitted to a vertical link 100. This link and the rod 110 which is actuated by the kickers, which in turn are controlled by the nature of the

card as a straight or reverse card, act upon a sector 119 to determine whether or not the entry is a debit or a credit; that is to say, whether it is to be printed in black or red. The sector 119 has flanges 115 and 116 similar to those on the sector 113 which controls the supplementary set of hammer locks. When the kickers actuate the rod 110 and links 111 backward, the link corresponding to the sector 119 draws back the upper end of a lever 120 whose lower end is connected by a pin and slot to a lower arm on the sector 119 and throws the sector down to bring the upper flange 115 into the central operative position. When there is a reverse perforation in the ledger the vertical link 100 is actuated upward, and through an angle lever 121 pivoted at 108^a and connected at its lower end with the pivot of the lever 120, such pivot is thrown backward and the sector 119 is thrown upward. Thus the kickers and the rod 110 actuate the sector in one direction, and the link 100 actuates it in the opposite direction. If both these instrumentalities operate at the same time they neutralize each other and leave the sector with its central unflanged portion in operative position. The sector 119 controls the listing ribbon by means of a rod 130^b connected to a rod 130 which is pressed forward by a spring and the plate 26 the same as the rod 118, the rod 130 running back to an arm 131 (Fig. 19) on the shaft 24 which actuates the ribbon of the listing mechanism. It controls also the mechanism for throwing one or another set (debit or credit) of adding wheels into operation, this control being by means of link 130^a pivotally connected at its forward end with the forward end of link 130.

In the same figure is shown a rod 132 running back to an arm 133 on a shaft 134, and determining whether the amount is to be added or subtracted to the previous balance. This is part of the balance-controlling mechanism and is controlled by the lower reversing holes O of the ledger sheet. The rod 132^b connected to the link 132 is also pressed forward by a spring under the operation of the plate 26 like the rod 118^b and the rod 130^b. Its forward movement or its failure to move forward is determined by a sector 122 whose movement is controlled by the vertical link 100^a coming from the pin at the rear of the machine 120 which enters a hole O when such a hole exists, and which is connected at its upper end to an angle lever 121^a, the lower end of which is connected with an intermediate point of a straight lever 120^a, the lower end 125 of which is connected by a pin and slot with a lower arm on the sector 122. The upper end of the lever 120^a is connected by a pin 123 with an upper arm of the sector 119. The balance sector 122 is therefore under 130

the control of the amount debit or credit sector 119, and the balance perforation in the ledger sheet. If there is such a perforation it indicates that the previous balance is a credit. If also the new amount is a credit the sector 119 will turn downward, carrying with it the upper end of the lever 120; the link 100^a will rise, causing a forward movement of the pivot of the lever 120^a coinciding with the forward movement of the upper end of the lever; and there will be no movement of the sector 122, and it will perform its normal operation, an addition. If the previous balance is a debit 15 and a new amount is a debit, there will be no actuation either of the balance-reversing link 100^a or of the amount sector 119, and the balance sector 122 will again remain stationary and cause an adding operation. If 20 however, there is a reversal of one of these elements and not of the other (that is to say, if the previous balance is a credit and the present amount is a debit, or vice versa) there will be only one element acting upon 25 the sector 122, and it will be removed to its reversing position with its flange 115 in line with the link 132.

Balance punching mechanism.

30 The balance is recorded on the ledger sheet both in perforations and in print. The punching mechanism is directly controlled by the perforations representing the previous balance and by the new amount. The 35 balance-printing mechanism is simply connected with the balance-perforating mechanism so as to be controlled thereby and to print the amount corresponding to the perforations.

40 The principal parts of the balance mechanism are shown in Fig. 20 and Figs. 38, 39 and 40. Four punches 135 are provided for each digit, and they are actuated in the desired grouping by means of a circularly 45 curved plate 136 provided with perforations arranged as in Fig. 20^a. The plate is moved up to bring any desired portion thereof in register with the punches, and is then pressed against the punches so that 50 the unperforated spaces of the plate select and operate the punches in the desired combination. Each plate 136 is provided with a rack 137 which when the plate is advanced engages a tapered centering pin 138 to insure 55 the correct register of the plate with the punches. The punches are retracted at the proper time by means of a comb 139 which engages collars on the punches, the comb being shown in Figs. 17 and 58 as a 60 plate extending across the punches and having side arms 140 pivoted on the sector-carrying shaft *h*. The forward movement of the shaft permits the forward movement of the punches, and the rearward movement

of the shaft withdraws the punches by 65 means of the comb. This construction facilitates the removal and sharpening of the pins or the substitution of new pins, it being only necessary to lift the comb 139, whereupon the punches may be taken out 70 and replaced. The movement of the punching plate 136, (Figs. 20 and 39) under the influence of the new amount and the previous balance, is effected by means of a pinion 141 engaged between two racks 142 and 143. 75 The rack 142 is moved with the amount sector, and the rack 143 is moved a distance corresponding to the previous balance. The travel of the pinion 141 therefore is the mean of the travels of the two racks, that 80 is to say, one-half the sum of their movements. The pinion 141 is mounted on an arm 144 which communicates its angular movement to the punching plate 136. The advantage of the described arrangement of 85 perforations will now be apparent. Although it requires four spaces (two vertical and two horizontal) upon the plate to control the group of four pins, yet it requires only a vertical movement of one 90 space to change the arrangement of the perforated and unperforated spaces. The distance between the successive lines of printing is two spaces, but the movement of the perforating plate in order to shift 95 from one figure to the next is only one space. Or, in other words, the perforating plate receives only half the movement of the amount printing sector in shifting from one 100 character to the next. Consequently no multiplying mechanism is necessary to change the half movement of the balance pinion 141 to a whole movement of the punching mechanism. One-eighth inch movements of 105 the punching mechanism are equivalent to 105 one-fourth inch movements of the amount printing mechanism. The rack 143 which takes off the previous balance is also arranged for the full spacing corresponding 110 to the printing mechanism.

The control of this previous balance rack 143 is similar to that of the controlling arms of the alphabet mechanism previously described. Since there are only four spaces which are to control nine digits, they must be divided first into groups and then into individuals as in connection with the alphabet above described. The individual controlling device 43 has its movement limited by rods 145 sliding in fixed guiding plates 146 and 147 and connected with levers 148 which connect at their lower ends with links 149 attached to vertical levers 150 at the rear of the pocket. There are four such levers 150 connected respectively to four feeling pins 151 located upon the line above that upon which the record is to be made, so that they are adapted to find and enter perfora-

tions representing the previous balance. These feeling pins 151 are of course located in the four corners of a square to correspond with the system of perforations adopted, but the corresponding sliding rods 145 are arranged vertically one above another so as to limit in succession the movement of the member 43. The four rods 145 are arranged, however, in five vertical spaces, the three lower rods being provided with pins 39 engaging the member 48 and actuating the stop member 46 for selecting one of the four groups into which the series of nine digits is divided. The member 44^a is provided with shoulders adapted to engage the upper end of the stop member 46 similar to the member 44 of the alphabet mechanism, but smaller because of the smaller number of characters to be handled in each group. The rod 52 holds up the forward arms as previously described, and a similar rod 152 holds down the arms carrying the punching sectors, both these rods being carried on arms which are fixed on the shaft *h*. The sector 153 which carries the punching plate 136 is loose on the shaft *h*. Its upward movement is limited (through intermediate devices) by the rear arm 154 which is part of the forward arm 144 that carries the balance pinion 141. For the purpose of so limiting the movement of the sector 153 it is provided with a pivot 155 upon which are carried two pivoted arms, an upper one 156 and a lower one 157, which have at their ends flanges adapted to engage stepped projecting portions 158 and 158^a of the member 154, each step representing a movement of two numbers. The angular movement of the arms 156 and 157 is controlled by their curved extensions 159 and 160, and these arms are provided also with notched locking portions 161. The locking of these arms is effected by means of a wedge-shaped lock or projection 162 carried upon a bar 163, which by suitable pin and slot connections is mounted to slide on the sector 153 which carries the punching plate. This locking bar is provided at its opposite end with a projecting pin 164 adapted to enter a notch in the arm 154 to lock the same to the sector 153 which carries the locking bar when the opposite locking projection 162 is free from the notched member 161. The slide 163 has a pin engaged in a slot of an arm 165 which operates the slide 163 and which is mounted upon a rod 166 upon an intermediate partition 167 in the machine. The one rod 166 carries an arm 165 for each decimal place or each sector or punching plate. The arms 156 and 157 are drawn inward by means of springs. Normally the rod 152 holds both the curved arms 159 and 160 which constitute the opposite ends of the members 156 and 157) in such positions that

the stop-arms 156 and 157 are held at the 65 rear of the circular path of the arm 154.

During the initial upward movement of the rod 152 the sector 153 is held locked to the arm 154 by the inward position of the slide 163 and the engagement of the lock 164 with said arm 154; but the arms 156 and 157 swing inward to their appropriate positions, and later the sector 153 carrying said arms moves upward beyond the arm 154 until stopped by the engagement of one of 75 said stop-arms 156 or 157 with one of the stepped members 158 or 158^a.

When the arm 165 is released as herein-after described, it is actuated by its spring 168 to throw the locking slide 163 to the 80 rear into position to lock said stop-arms in their appropriate angular positions on the sector 153 carrying the same, which then moves upward beyond the member 154 whose final position is determined by the balance 85 pinion. Upon the forward movement of the shaft *h* therefore which carries these several parts, the punching plate will engage and drive the appropriate punches through the paper. The release of the arm 165 which 90 effects the locking and unlocking of the parts is effected by means of an arm 169 mounted on the same shaft with said arm 165.

The punching plate 136 is of sufficient length to include two and a half series of 95 spaces each corresponding with the figures from 0 to 9.

Where the ordinary operation occurs, the adding of the new amount to the previous balance, the movement of the punching plate 100 is limited to the first two series of spaces.

When the new amount is to be subtracted from the previous balance, as the amount 231.40 from the previous balance 766.75 in Fig. 3, it is done by adding the complement 105 (the difference between the capacity of the machine and the subtrahend). Thus the complement of 231.40 is 99768.60, which added to 766.75 gives 00535.35; or suppressing the zeros, 535.35, the new balance; and 110 the machine punches and prints this. The result may be called a normal subtracting operation, and is obtained according to the algebraic equation

$$a + (c - b) = (a - b) + c,$$

115

(*a* - *b*) being a positive quantity, and the constant *c* being eliminated by the machine's passing beyond its capacity.

In applying the same theory of operation 120 to a case where the new amount is to be subtracted from the previous balance but is larger than that balance, we meet with a further difficulty. At one point in Fig. 3 for example the previous balance is a debit, 125 1276.40, and the new amount a larger credit, 1500.00. The complement of 1500 is taken, equal to 98,500.00. Adding this to the pre-

vious balance 1246.40, gives 99776.40, and the machine must record not this sum as in the previous case of subtraction of a smaller subtrahend, but its complement, 223.60, which is the true difference. The operation is indicated algebraically thus,—

$$a + (c - b) = (a - b) + c,$$

($a - b$) being a negative quantity, so that 10 this difference must be also subtracted from c and the complement recorded. This complement is negative, which means that on the books the new balance will be a credit where the previous balance was a debit (or 15 vice versa).

Thus for a simple subtraction of a smaller subtrahend the machine must determine one complement, that of the subtrahend; for a subtraction of a larger subtrahend the machine must determine first the complement of the subtrahend and then the complement of the sum of the previous balance plus the first complement. In order to register the complement of a number however the printing plate does not move through a number of spaces equal to such complement, but through a space depending on the relative positions of the number and its complement, bearing in mind that the plate must move 25 always forward. Thus by referring to Fig. 59 it will appear that if the plate has first moved to zero (no movement) the registration of the complement of this, 9, calls for a further movement of nine spaces; but from 30 1 to its complement, 8, is a movement of only seven spaces; from 2 to its complement, only five spaces; from 3 to its complement, three spaces; and from 4 to its complement, one space. Then commences a second series of 35 movements. From 5 to its complement on the following part of the plate is a movement of nine spaces; from 6 to its complement, a movement of seven spaces, and so on as before. The complementary movements of the plate therefore proceed in steps diminishing by two from nine spaces to one space. The plate is long enough for the determination and corresponding movement of a first complement, the adding of this to 40 the previous balance, and the determination and corresponding movement of a second complement.

The mechanism for effecting these complementary operations is shown principally in 55 Figs. 20, 38, 39 and 40, and consists of a number of parts which determine the time when the arm 165 shall move to the rear and lock the arms 156 and 157 in fixed angular positions on their carrying plate 153.

60 The rack 142 is moved downward according to the new amount to be recorded by a depending link 142' which engages (with a lost motion of one step for "carrying" purposes as hereinafter explained) a sector 187

mounted loosely on one of the shafts 173. 65 These shafts 173 are rocked through an angle corresponding to the capacity of the machine by means of arms 219 (Fig. 18) fixed on said shafts and connected to a vertical link 220 which is connected by a spring 70 and a pin and slot connection to an arm 221 fixed on the shaft h . Adjacent to each sector 187 is a sector or arm 186 mounted on a sleeve 185 on the same shaft 173, which sleeve at its other end (Fig. 19) is connected 75 to an arm 184 by which the sleeve is rocked with the amount sector, their forward ends being connected by a link 183. Between the arms 186 and 187 is an arm 221 fixed on the shaft 173 and rocked thereby through an 80 angle corresponding to the capacity of the machine. From the shaft 173 and its sleeve 185 the appropriate movements are transmitted through arms 221 and 186 to the sector 187 and thence through the link 142^a 85 to the amount rack 142.

Normally the arms 186 and 187 are locked together by a lock 188 having a sliding support at one end on the shaft 173 and at the other end between a pair of flanges 222 carried by the arm 187 and having its end normally extending between similar flanges 223 on the arm 186. The locks 188 on the several shafts are all connected by links 224 to a rod 225 carried by arms 226 on the shaft 134 95 previously referred to and which remains stationary when the amount is to be added to the previous balance and which is turned to the left when the amount is to be subtracted, and thus pulls the links 224 to the 100 rear and withdraws the several locks 188 from engagement with the arms 186 on the several shafts.

When the reversing mechanism fails to 105 actuate the shaft 134 and leaves the lock 188 in the position of Fig. 38, the arms 186 and 187 are moved together and the exact movement of the amount printing sector is communicated to the amount rack 142 of the balance mechanism. The intermediate arm 110 221 which is fixed on the shaft 173 swings down between the two arms 186 and 187 without effect.

When however the new amount is to be 115 subtracted from the previous balance and the shaft 134 is actuated to withdraw the lock 188, then first the arms 186 and 221 move downward together and without influence on the arm 187, until the arm 186 has moved the full distance corresponding to the 120 amount; whereupon, second, the arm 221 engages the arm 187 and carries the latter through an arc corresponding to the remaining movement of the arm 221. This remaining movement is the complement of the 12 amount,—the difference between the capacity of the machine, represented by the travel of the arm 221, and the amount represented by

the travel of the arm 186. Consequently the rack 142 adds to the previous balance the complement of the amount, which is equivalent to subtracting the amount.

- 5 The engagement between the arms 221 and 187 is effected by a pivoted dog 224 on the former and a rack 225 on the latter. The dog has an upwardly projecting arm 226 entering a socket in the lock 188 which holds 70
 10 the dog out of engagement with the rack, a spring 227 tending to throw it into engagement and a forward arm 228 in the path of the end of the arm 186. While the lock 188 is forward or the arm 186 is moving 75
 15 down with the arm 221 the dog is held back; but when the arm 186 ceases to move with the arm 221 the dog 224 is released and springs into engagement with the rack 225.
 When the sector 153 carrying the punching plate 136 of any decimal place moves upward beyond the first series of spaces, indicating a number equal to or greater than 80
 20 ten, the number 1 must be carried or added in the next higher decimal place. This operation is effected by links 229 (Figs. 20 and 38) connected at their upper ends to the several sectors 153 and each connected at its lower end by a slot nine spaces long to the arm of an angle lever 230 the other arm of 85
 25 which is connected to a link 231 engaged in a curved slot 232 in a slide 233 on the face of the arm 187 of the next higher decimal place. Initially the end of the carrying slide 233 engages a shoulder on the link 142^a
 30 and holds the latter up with the pin 234 on the arm 187 in the lower end of the slot 235 in the link. When the sector 153 moves upward more than nine spaces the link 229 actuates the angle lever 230 to withdraw the 90
 35 carrying slide 233, whereupon the spring 236 pulls the link 142^a downward one space to bring the pin 234 to the top of the slot 235, thus causing the amount rack 142 to have an additional movement of one space beyond 95
 40 that of its actuating arm 187. On the returning upward movement of the arms 187 they are stopped by fixed stops 237 on a wall 238 extending from right to left, the several stops being in line with noses 239
 45 on the arms 187. The racks 142 move one step farther, lifting the links 142^a to their initial positions, and the carrying slides 233 are shoved under the shoulders of said links by means of springs 240. The support for 100
 50 the crank lever 230 is a rearward arm 241 pivoted on the sleeve 185 by which the amount arm 186 is actuated, and this arm 241 is normally drawn down by a spring 242, the outer ends of the arms for the different decimal places resting on a stepped support 241^a. When the link 229 continues to rise after 105
 55 tripping the lever 230, the spring 242 allows the arm 241 to rise with said link.
 When a smaller amount is subtracted from a larger previous balance, the sum of the

complement plus the balance is greater than the capacity of the machine. The nature of the balance (as a debit or a credit) is not reversed in this case. But when the subtrahend amount is larger than the previous balance, the sum of the complement plus the said balance is less than the capacity of the machine; and the nature of the balance is reversed. The passing of the mechanism beyond the capacity of the machine thus 70
 60 distinguishes one case from the other and is utilized in causing the machine to record the sum in the first case and the complement of the sum in the second case. 75

The sector 153 of the highest decimal place is provided with a link 229 similar to those used for carrying one from the lower decimal places (although of course there is no higher decimal place to which one may be carried) and this link also actuates an angle lever 230 and link 231. This link 231 engages the lower arm of a locking lever 243 the upper end of which has a flange adapted to overlie a short lip 244 on the arm 169 when the locking lever is actuated; that is, by the passing of the mechanism beyond the capacity of the machine. 80

The arm 169 (Figs. 20 and 40) is normally locked by a second flanged lever 245 engaging a lip similar to the lip 244, the upper end of the lever being moved backward to a point between the two lips when it is desired to release the arm 169. The lever 245 is actuated by a link 246 connected to its lower end and to an arm 247 on the shaft 234 100 which is rocked to the left when a subtracting operation is to be effected. 100

Thus the arm 169 is released only in the case of a subtracting operation when the amount is greater than the previous balance (the mechanism does not pass beyond the capacity of the machine); being the case in which the balance is to be reversed. As long as the arm 169 is held down the shaft 166 is stationary and the arms 165 thereon are held in their forward positions; and the locking bars 163 are held forward to lock each sector 153 to the corresponding arm 154; so that the punching plate carried by said sector moves with the balance pinion 141 which 110 actuates said arm; and the stop-arms 156 and 157 (although they pivot freely) never come into play, since there is no relative movement between the sector 153 and the arm 154. 115

It is only when a subtraction is performed (releasing the lock 245) and the mechanism does not move beyond the capacity of the machine (leaving the lock 243 released) that the stop-arms 156 and 157 come into play; 125 their function being to measure the complement desired by counting off the spaces through which the punching plate must move in order to record the complement of the sum represented by the movement of the 130

balance pinion and its rear arm 154. A locking arm 248 rocks with the shaft *h* and has a slot engaging a pin on the arm 169 so as to hold the arm down long enough to allow the proper setting of the locks 243 and 245, and releasing the arm 169 only after the balance pinion and its arm 154 have assumed their final positions. The rod 152 will have traveled upward and the stop-arms 156 and 157 will have assumed their proper angular positions. Thereupon, on the release of the arm 169, the springs 168 will turn the shaft 166 and throw the arms 165 to the rear to lock the stop-arms 156 and 157 in their assumed angular positions, and to release the sector 153 from the arm 154, thus allowing the sector to move upward through a further space determined by the positions of the stop-arms 156 and 157 relatively to the stepped portions 158^a and 158 of the stationary actuating arm 154.

Fig. 40 shows this advanced position of the sector 153 with the stop-arms locked thereon and one of them, 157, engaging the stop member 158 and thus limiting the upward movement of the sector.

Fig. 60 illustrates on a larger scale parts of this mechanism and its operation. Flanges 156^a and 157^a only of the stop-arms 156 and 157 are shown, and these are in their initial positions. As the rod 152 swings upward to allow the arms 156 and 157 to swing inward the sector 153 carrying said arms also swings up to a distance corresponding to the number whose complement is to be recorded. The rod 152 swings through an arc corresponding with the capacity of the machine, and its movement beyond the final position of the sector 153 corresponds with the desired complement; and it is this differential or complementary movement which is measured in the angle assumed by the arm 156 or 157. The movement of the stop-arm 156^a or 157^a is commensurate with the difference between 10 and the figure at which the sector 153 stands. When the sector stands at the last 9 of the series there is the slightest movement, one step, by the stop 156^a, and a movement of the sector only one step (so as to bring the following zero on the printing plate to operative position) beyond the arm 154, being then stopped by the engagement of 156^a with the first shoulder of 158. When the sector stands at the previous 8 the stop 156^a moves two steps, and the sector a distance of three steps farther, to bring the number on the printing plate into play, as will be clear from Fig. 59, and so forth. This series of movements causes the passage of the stop 156^a over the stepped members 158 and 158^a (after which it maintains always the same advance beyond 157^a) and then gives 157^a a first double movement (by the jog in the arm 160) to bring it into

line with the first step of 158 and subsequent single movements, as for the stop 156^a.

The upward movement of each of the sectors 153 carrying the balance punching plate is effected by springs acting on the corresponding balance printing sector; the punching sectors being connected to the printing sectors through their forward arms 170, links 171 and arms 172 to sleeves 172^a, as previously explained.

Balance printing sectors.—The punching sectors 153 are provided with forward arms 170 (Figs. 20 and 38) connected by links 171 with arms 172 mounted on sleeves 172^a on shafts 173 and communicating to said sleeves the same angular motions as are received by the sectors. There are five shafts 173, one for each digit of the balance punched and printed, and there is a separate connection from each of the punching sectors to a sleeve on a corresponding one of these shafts. Each sleeve 172^a is in turn connected to a balance printing sector *t* (Fig. 22) by means of a forward arm 174, link 175, and arm 176, a downward strain being exerted on the arms 176 by means of springs 177, whereby the printing sectors and the corresponding punching sectors are advanced until stopped in the manner above described by the balance pinions and their rear arms 154.

Separate individual stops 178 are provided engaging the followers 76 of the hammers of the several printing sectors, each stop 178 consisting of an arm pivoted upon the uppermost shaft 173 and adapted to be raised out of its locking position by means of a lateral projection 180 which is under the pull of a spring 181 and which carries (for the uppermost shaft) a lateral pin 182, overlying the corresponding arm 184; so that only when the proper arm 184 is lowered will the hammer be released. For the shafts 173 below the uppermost one the motion is transmitted in the manner indicated in Fig. 19. The arm or lateral projection 180 of the stop 178 is connected by a link 180^a and a pin and slot connection with the arm 184 on the appropriate shaft 173. This arrangement is repeated for each of the lower four shafts and has the same effect as the pin 182 shown in Fig. 19 resting directly on the arm 184 on the uppermost shaft.

The amount printing sectors (Fig. 19) are provided with similar individual locking members 178 mounted on the same shafts 173. The relative positions of the amount printing mechanism, the balance perforating mechanism, and the balance printing mechanism, will be clear from Fig. 23, which shows the location of the partitions 167 and 167^a between the planes of which lies the balance-punching mechanism. The amount printing sectors are provided each with a forward arm 56, and this forward arm is

connected by a downward link 183 with an arm 184 upon a sleeve 185 upon one of the shafts 173; there being a separate sleeve and connections to correspond with each decimal place.

Recording sheet carrier or pocket and lifting frame.

- The pocket R which carries the recording sheet or ledger sheet is fixed between the side frames V and V'. For feeding the paper upward step by step, perforations are made in the edges of the sheet as previously described, the pins b being used for this purpose. As the pins b are retracted, a pair of lifting pins enters the perforations made thereby, lifting the sheet a distance of one line, and hold it until the following line is printed and the lifting perforations are made, whereupon it repeats the previous operation. The lifting frame is shown in side elevation in Figs. 14, 15 and 37 and in perspective in Fig. 57, and comprises a cross-bar 189 carrying the lifting pins 190 and carried at the ends of upwardly projecting arms 191 supported near their lower ends from links 192 which are pivoted at their forward ends and held up at their rearward ends by springs 193. The arms 191 are adapted to be locked down by spring hooks 194 engaging suitable notches in the arms. The upper ends of the arms 191 are held forward by springs 195. A three-armed lever 196 Figs. 14 and 15 is arranged to engage a pin 197 upon the arm 191 at each side of the machine to press the frame to the rear and release the recording sheet. The lever 196 at either side of the machine may be operated by pressing down its rear end by hand, or by lifting its forward end either by hand or by means of a member 197^a carrying a pin 198 adapted to bear upon the suitably curved under surface of the lever 196; the member 197^a being always moved to the rear when the machine is operated, by means of a link 199 connected with the arm 67 which, as has been previously explained, is operated by the pulling down of the member 64 when the hand lever is operated. The actuation of the member 197^a takes place gradually and is completed toward the end of the movement of the operating handle when the sheet has been punched and a new set of lifting holes made therein on the next lower line. The continued movement of the member 197^a causes it to strike a pin 200 carried on the arm 191 and thus to depress the arm and with it the lifting pins to a point coinciding with the line just recorded. On this downward movement the locks 194 engage the opposite sides of the lifting frame and hold it down. The backward movement of the operating handle of the machine withdraws the member 197^a to allow the

frame to swing forward (later, on the withdrawal of a stop hereinafter described) and the lifting pins to enter the new holes. Toward the end of this backward movement of the handle the lower ends of the arms 191 are released from the locks 194, and the springs 193 lift the frame and the sheet to the new position.

The withdrawal of the locks 194 is effected by means of links 201 which are connected with the vertical arm of the bent lever 31, which, as before described, is controlled by the movement which advances the controlling pins into the card pocket, which movement takes place early in the operation. The advance of the controlling pins is caused by the swing of the link 30 backward (Fig. 14) and this also causes the pin which is carried in the bent lever 31 to travel idly in the slot in the link 201. The continued movement merely causes the link 201 to slide upon the pin 202 on the lower end of the arm 191 which supports its rear end slightly beyond the position of Fig. 14 to that of Fig. 37. When the side members 191 of the frame are lowered and with them the pins 202, the links 201 are drawn down by their springs 203 until the notches 204 in the lower edges of said links rest upon pins 205 projecting laterally from the hooks 194. The links 201 therefore then rest in this position ready for operation. On the retractile movement of the operating handle and the forward movement of the link 30 the notch 204 engages the pin 205 and pulls the hook 194 out of engagement with the upright 191, allowing the frame to move upward. The rearward movement of the link 201 and the link 30 and the forward pressure upon the controlling pins is effected by a cam 212 mounted upon the operating shaft and engaging a roller at the point of connection of the link 30 with the angle lever 31. The member 197^a whose withdrawal is also necessary to permit the frame to move upward moves slowly. It is desirable that the upward movement shall be a quick one. Therefore the mechanism actuated by the link 201 is provided, and is arranged to release the frame and permit it to move upward only after the member 197 has been first withdrawn.

A frictional device is provided for holding the sheet lightly in order to permit the withdrawal of the punching pins and the insertion of the lifting pins without the sheets dropping to the bottom of the pocket. This frictional device may consist of one or more curved arms or plates 206 (Fig. 14) pivoted at 207 upon a shaft whose arm 208 is connected by a link 209 with an arm 210 normally held down by a spring 211.

The arm 210 serves as a stop to prevent return of the frame 189, 191 forward when

there is no sheet in the pocket. For this purpose its end is in the path of a pin 211^a carried on the end of an arm 211^b and lying in a vertical slot in the arm 191. By the 5 insertion of a sheet and the pressing back of the plates 206 the stop arm 210 is lifted, so that the frame swings forward and its pins enter the first perforations in the sheet. Only when the sheet is finally withdrawn 10 can the arm 210 be again lowered; in which position it engages the pin 211^a as the lifting frame moves outward, and holds the frame outward for the easy insertion of a new sheet without interference from the lifting pins.

15 Interference with a new sheet by the feeling pins 98^c and 98^d entering the pocket is avoided by mechanism illustrated in Figs. 14, 33 and 34. Each of the levers 98^a and 98^d carries a pivoted pawl 282 the forward 20 end of which initially engages the end of an arm 283 pivoted on the lever 98^c or 98^d and which is held back as in Fig. 34 by a rod 284 mounted in ears at the rear of the members 191 of the frame which feeds the recording sheet. When this frame can move inward the levers 98^c and 98^d can also yield. The frame and the rod 284 move inward at each operation of the machine. Whenever 25 the lever 98^c is retracted after a forward movement with the arm 283, the pawl 282 drops behind the end of the arm 283 and must be restored. This is effected by the downward and inward movements of the rod 284 (with the feeding frame) which bring 30 this rod under the end of a lever 285 whose slot carries a pin on the pawl 282, and by the following upward movement of the rod 284 which lifts the lever 285 and pawl 282, so that when the rod 284 next swings back it 35 40 pushes the arm 283 under the pawl to the initial position. The levers 98^c and 98^d are notched as shown to make room for the movements of the rod 284. The most important function of this mechanism is to 45 insure the entrance of the pins 98^c and 98^d at the very beginning of the operation, as soon as the recording sheet is properly placed in the pocket; so as to set the debit and credit mechanism and insure its control 50 of the subsequent operations.

"No-card" lock.

The machine is locked against operation when there is no controlling card in the 55 pocket Q, or when this card is not accurately centered. This lock is controlled by the shaft 108 (Figs. 14 and 18). Mounted on this shaft within the machine is an arm 213 which is restrained from forward movement 60 by a lever 214 which engages a projection 215 of a second arm 216 which is rigidly connected with the arm 213, the lever 214 being held up by a spring 217 and having its forward end projecting through a vertical

slot in the lower part of the pocket so that 65 it may be engaged and depressed out of operative position by pushing a card down firmly to the bottom of the pocket. The upper end of the arm 213 is forked or perforated and carries a setting pin 218 adapted 70 to enter a setting hole B in the card. If, however, the card be not properly placed in the pocket the setting pins 218 will not register with the setting holes B and will not move forward although normally pressed 75 forward by the spring surrounding it. Consequently the arm 213 will not be pushed forward and the lock will not be released. It requires therefore a conjunction of two 80 movements, namely, the downward movement of the lever 214 and a forward movement of the setting pin to effect the unlocking of the mechanism, and these two operations can only take place when a card is in the pocket and properly locked therein. 85

For retracting the members 213 and 216 a hook 219 is provided pivoted at its rear end upon the movable plate 26 and resting at an intermediate point upon the lever 214, so that as this lever is lowered the hook when 90 advanced will drop over the projection 215 and, when the plate 26 is retracted, will withdraw the projecting portion 215 so far that the lever 214 will snap up under it and engage and hold it from forward movement. 95

The same shaft 108 serves to prevent the entry of the feeling pins 98^c and 98^d into the recording sheet pocket R, through the intermediate mechanism shown in Figs. 14, 100 33 and 34. The arm 70 of the shaft 108 actuates a link 277 extending to the rear and there connected to an arm 278 on a shaft 279 which carries arms 280 and a rod 281 lying normally against the inner edges of 105 the upper parts of levers 98^a and 98^d to prevent their inward movement, and permitting such inward movement only upon the rocking of the shaft 108 by the mechanism above described. 110

Reversing punches.

The reversing punches which make the perforations N and O in the column M (see Figs. 2 and 3) are the punches c and c' of 115 Figs. 17, 21 and 33. The upper punch c operates when the sheet is a reverse sheet, when it is to reverse the effect of the card; the lower punch c', when the balance is the reverse of its normal character, as debit and 120 credit.

A reverse sheet starts with a perforation N in the top line, and this is repeated for each line. The repetition is effected by the entrance of the feeler 98^c into the upper perforation N of the previous line. This 125 swings the lever 98^a and shifts the link 98 as in Fig. 33, acting through a crank lever

249 and vertical link 250 to swing a locking lever 251 forward so that the locking pin 252 carried thereby overlies a shoulder 253 formed on a depending portion of a punch-
 5 actuating arm 254 which is pivoted on the shaft *h* and has a flange 255 in position to engage the punch *c* and actuate it when the shaft *h* is swung to the rear. When however there is no previous perforation for the
 10 reversing feeler 98° to enter, and the locking pin 252 remains in the inoperative rearward position of Fig. 21, a spring 256 lifts the arm 254 when the latter is released by the rising of the rod 152, and the flange
 15 255 passes above the punch and fails to actuate it.

For actuating the balance-reversing punch *c'* a similar arm 257 is used, pivoted on the shaft *h* and having a pair of separated
 20 flanges 258 and 259 either of which may actuate the pin, but both being normally in inoperative positions as in Fig. 33. The arm 257 is actuated by a link 260 controlled by the shaft 166, which, as previously de-
 25 scribed, is given a rotary movement to the right after a short initial rotation of the shaft *h* whenever a reverse balance, that is a credit, is to be recorded, said link 260 being controlled also by the previous bal-
 30 ance reversing hole in the recording sheet.

The shaft 166 has an arm 261 carrying a pin 262 in a slot 263 in a link 264 attached to the link 260, and is connected by a spring 265 to said link 264. Supposing there is no
 35 reversing punch in the previous line of the record sheet, a sliding pawl 266 engages a nose 267 on the link 264 (Fig. 21), and when the arm 261 is advanced it moves the punch-operating arm 257 down to bring the
 40 upper flange 258 thereof into play. The arm 261 will at the end of the operation be retracted to bring the punch-operating arm 257 to its middle inoperative position. Sup-
 45 posing the next amount to be a debit smaller than the credit balance last recorded, like the debit \$139.60 in Fig. 3, against a credit balance of \$223.60; there is a simple sub-
 50 traction to be performed without the taking of any final complement and without rotat-
 55 ing the shaft 166. Nevertheless the balance remains a credit, and a perforation O must be made. To provide for this entry of the feeling pin 98° into the perforation O of the previous line (Fig. 33) and the swing of
 60 the lever 98' and link 98" acts through angle lever 268, link 269, and angle lever 270, to withdraw the pawl 266, whereupon the spring 265 pushes up the punch-operating arm 257 till its lower flange 259 comes into play. The parts are restored after each operation by the downward movement of the rod 152 Fig. 21 on the arms 254 and 257.

The printing ribbons for the balance printing mechanism are shifted by a pair

of vertical slides 271 (Figs. 22 and 63) 65 carrying the ribbons at their upper ends and actuated by arms 272 on the shaft 273; which is actuated from the punch-operating arm 257 just described (see Figs. 21 and 33). The shaft 273 has arms 274 and 275 70 each engaging by a pin-and-slot connec-
 75 tion the forked lower end of the link 260. The arm 273 is pulled down by a spring 276 to normally hold the black ribbon operative. Fig. 21 shows the normal position, the arm 257 being in its intermediate position. Moving the punch-operating arm 257 up pulls up the arm 275 of the ribbon shaft. Moving the arm 257 down from the intermediate position forces down the arm 274 80 of the ribbon shaft. In either case the latter is rocked to bring the red ribbon into play.

Adding wheels.

85

The adding wheels are in two series indicated as a whole by the reference numerals 286 and 287 (Figs. 16, 19, 20, 24, 35 and 36). In Fig. 35 they are shown in detail, and only two wheels are indicated in each 90 series for the sake of clearness. The shaft 288 of the upper series is mounted in a frame comprising arms 289 pivoted on the shaft 34 carried in the mushroom frame *j* (Figs. 14 and 18) which swings for- 95 ward to punch and print the record. The shaft 290 of the lower series of wheels is mounted in a similar frame comprising arms 291 pivotally mounted on the same shaft 34. Below the wheels are located seg- 100 mental racks 292 connected to the amount sectors. One series of wheels or the other is dropped into engagement with the racks when the latter have assumed the final positions, and is actuated by the return move- 105 ment of the racks.

Both frames 289 and 291 stand normally above the racks, being held up by arms 293 on a shaft 294 which is carried in the frames *j* and which has at one end an arm 295 110 (Fig. 14) held up by a spring 296 and pressed down on the rearward movement of the frame by a pin 259a on the toggle link *k* to release both series of adding wheels. At the beginning of the next operation the 115 shaft 34 is turned by the mechanism previously described, so as to lift arms 297 which are fast thereon, so that the rod 298 carried by said arms, which is in engagement with the lower edges of both the frames 289 and 120 291 lifts said frames with their wheels.

Mechanism is illustrated for selecting one or other series of adding wheels according as the amount to be recorded is a debit or a credit. The frames 289 and 291 are pro- 125 vided with hooks 299 and 300 respectively, and locking pins 301 are adapted to enter the hooks of one or the other of the frames

alternatively and hold it up. The pins 301 are carried in arms 302 on a shaft 303 which normally stands in the position of Fig. 35 to hold up the upper wheels 286. The ends 5 of the shaft 303 are mounted in the frames *j* and it is provided at a point in line with the reversing punches (Figs. 21 and 33) with an arm 304 connected by a link 305 with a lever 306 mounted loosely on the shaft *h* and actuated by the link 130^a as 10 previously described when a reverse entry is to be made; thus locking the lower adding wheels and freeing the upper ones. Fig. 36 shows this position.

15 Throughout the same number of decimal places as are contained in the amount mechanism, "carrying" devices are necessary, to act whenever the number to be registered in any column passes from 9 to 0. The adding wheels in excess of such number of decimal places, however, do not have such devices, but simply a secondary shaft carrying loose 20 gears communicating each tenth step of one registering wheel to the next higher registering wheel. These supplementary gears 25 are indicated at 307, Fig. 24.

The special carrying devices are shown best in Figs. 19 and 35. Between each pair of wheels is an arm 308 loose on the shaft 34 and pulled up by a spring 309. One such arm may act for wheels of both series 286 and 287, where as in the present case the two series are to be used alternatively. The racks 292 are carried movably on their supports 310, being guided by pin and slot connections as shown and each has a lug 311 normally engaging the end 312 of the arm 308 and held there by a spring 313 one end of which is fastened to the rack 292 and the other end its support 310. When the machine is operated the rack 292 is carried forward free of the arm 308. On the return the rack engages and operates the appropriate adding wheel, and if the latter turns past 40 the number 9 it lowers that arm 308 which is in line with the rack 292 of the next higher decimal place. This brings into line with the lug 311 a shoulder 314 of the arm 308 and allows said rack to move one step farther than usual, thus carrying 1 on the adding wheel with which it gears.

45 Each arm 308 is pressed down by means of projections 315 carried thereby facing the side face of the next lower wheel, on which 50 side face are wedges or cams riding over the projections 315. The arm is held down throughout the remainder of the stroke by a pawl 316 loose on a shaft 317 and pulled forward by a spring 318, and engaging a 55 flange 319 on the arm. On the next stroke 60 the several pawls 316 are withdrawn by pins 320 carried on arms 321 on the shaft 317. The latter is carried in the frames *j* Fig. 14 and provided at one end with an 65 arm 322 connected to the toggle link *l* so as

to withdraw the pawls 316 on the printing or recording stroke, and to free them on the return or registering stroke.

Single space recording sheet and mechanism.

70 In the sheets shown in Figs. 2 and 3 the listing column G is as wide as the portion of the controlling card including the three entries,—distribution, name of debtor, and name of creditor; and the machine prints 75 these entries in corresponding portions of the wide column G. For example, when the distribution is printed it occupies the first section as in Fig. 3; when the name of debtor is printed it occupies the second section 80 as in Fig. 2; and the name of creditor would occupy the third section. This makes the recording sheet unnecessarily wide, and I propose in practice to make the column G only wide enough for one of the three 85 entries in question; the machine requiring but one set of types, located in front of said column G and adapted to be separately controlled by any one of the three columns of the controlling card. The machine will then 90 automatically select the controlling mechanism desired, by the selecting mechanism under control of the card and sheet herein-after described, or by any other suitable 95 selecting mechanism.

Fig. 42 shows a sheet similar to that of Fig. 3 except that the column G' is made only wide enough for one of the three items,—distribution, or the name of either party; and except for the provision of an 100 additional column G² containing the journal number of the entry. The journal entry is indicated in the same manner and by the same sort of mechanism as the date. Abbreviations in common use are shown, such as 105 "M. R." for merchandise returned; "30 Nt." for a 30-day note; "Dis." for discount; and a star for cash or a check.

110 As previously stated, the wide column G of Figs. 2 and 3 may be reduced to a column of single width, making a sheet such as is indicated in Fig. 42; this figure having however an added column G² for journal numbers. The column G' corresponds to the column G of Figs. 2 and 3, except for the reduction in width previously referred to, and the columns H, J, K, L and M correspond with those in Figs. 2 and 3. The sheet is exactly that of an ordinary ledger 115 except for the continuous balance and the 120 perforated columns.

The mechanism for making such a recording sheet may be operated by the same controlling card as previously described, and requires comparatively little departure from 125 the mechanism already described. The altered mechanisms are shown in Figs. 41, 43, 44 and 45. Fig. 44 illustrates the relative arrangement of the controlling and recording mechanisms. The parts bracketed un- 130

der the letter W' are the date mechanism, under W^2 the journal number mechanism, and under X' the listing mechanism. The groups W' and W^2 are identical in detail with the controlling pins, type carriers and intermediate mechanism previously described; the sectors q' and q^2 which carry the types being merely offset sufficiently to bring them close to the group X' constituting the alphabet mechanism; the lateral arms for effecting the offset being shown at 323 and 324.

The sectors r' which carry the types of the alphabet are only one-third as many as in the arrangement of Fig. 17, and each sector r' is adapted to be actuated by the controlling pins of the corresponding decimal place of any one of the three items on the card, namely, the distribution, as "merchandise"; the buyer, as "John Smith"; or the seller, as "John Wanamaker". The controlling pins are substantially the same as in Fig. 18, and for each decimal place in each of the three items there are the arm 44 and mechanism for limiting its downward movement, as previously described. Only instead of the arms 44 operating the type-carrying sectors directly, these arms act, as shown in Fig. 45, upon flanges on the lower edges of arms 44^a , 44^b and 44^c , the arm 44^a being connected directly to the type-carrying sector r' , and the three arms 44^a , 44^b and 44^c being connected by plates 325 which are fastened to arcs 326 extending upwardly from the ends of the arms 44^a , 44^b and 44^c . The arcs 326 for the successive decimal places overlap each other, as indicated in Fig. 45, in which only the lower set of plates 325 is shown with the arcs 326 of the next higher decimal place extending above said plates.

The mechanism shown in Fig. 41 determines whether the machine shall be operated under control of the distribution, the debtor or the creditor column of the controlling card; that is to say, whether the machine shall record the character of the goods, the name of the buyer, or the name of the seller, and this is done by locking the arms 44 corresponding to any two of the sets of controlling pins, so that even though the controlling pins enter the perforations in the controlling card yet the arms 42 will not move and will have no effect upon the record. The shaft 330 of Fig. 41 is located at the upper front part of the machine, as indicated in Fig. 43, and carries three pairs of arms indicated respectively as 331, 332, and 333, each pair being mounted on a separate sleeve on the shaft and carrying respectively rods 334, 335 and 336. In the sectional view, Fig. 43, one of the arms, say 331, is indicated, and the corresponding rod 334. For the other arms there are similar arrangements connecting them

with the corresponding arms for operating the type-carrying sectors. The arms are under the tension of springs 337 tending to draw them forward, and (after a slight delay provided for by the pin and slot connection) to permit the forward movement of a link 338 which is connected to a pawl 339 engaging the arm 44 and attached to a spring 340 which normally endeavors to withdraw it. This pawl 339 corresponds in function also to the pawl 35 of Figs. 18 and 20, in that it prevents the movement of the arm 44 until one or more of the controlling pins has advanced.

The pair of arms 333 correspond with the distribution column of the controlling card, the arms 331 and 332 with the creditor and debtor columns respectively. The recording sheet or ledger sheet, which is perforated as previously described when it is a reverse account, and which is not perforated when it is a straight account, determines thereby that there shall be recorded the distribution in one case and the debtor or creditor in the other case. A shaft 341, Fig. 41, is arranged to oscillate under the direct influence of the pin 98^c (Fig. 33) which enters the reversing perforations in the ledger sheet. The rocking of the shaft 341 actuates arms 342 and 343 connected therewith, the former being connected by a link 344 to an arm 345 loose on the shaft 330 and carrying a stop-pin 346 by which the second and third columns of the card may be suppressed when this stop pin is moved downward. The downward movement of this stop-pin corresponds with the downward movement of the arms 342 and 343, and the latter through a link 347 and an arm 348 carried on the same sleeve as the arms 333, swings the latter forward so as to permit the operation of the printing sector from the first of the three columns of the card.

The shaft 349 is controlled by the nature of the controlling card; by its being a straight card or a reverse card; that is to say, by its having the first two holes D punched or the second two holes, or etc. The shaft 349 may be rocked, for example, by connection with the rod 118, which, as shown in Fig. 32, is under control of the perforations in the controlling card. It may be called the secondary control shaft and is operated substantially simultaneously with the principal control shaft 341. It carries an arm 350 to which are connected links 351 and 352, the former running up to the rear of the shaft 330 where it is connected by a pin and slot to the arm 353 on the sleeve carrying the arms 331. The link 352 is connected at the forward side of the shaft 330 to an arm 354 which is fast on the shaft 330 and is thus connected to the arms 332, the latter being also fast on said

shaft, as is indicated by the set-screws shown. Normally the pins which connect the arms 353 and 354 with their controlling links stand at the middle of the slots in which they travel. When the stop-pin 346 is depressed the arm 354 is held down and likewise the arm 353, which for this purpose extends clear around to the front of the shaft. Both the arms 331 and 332 are thus suppressed. When the stop-pin 346 is moved upward the arms 331 and 332 are both released. At the same time however the links 351 and 352 both move either upward or downward a distance equal to half the length of the slots therein. If they move upward the arms 331 are prevented from yielding to the forward pull of their springs 337, but the arms 332 are free to so yield. If the links 351 and 352 move downward the opposite operation takes place.

Other modifications of controlling cards and recording sheets.

After the controlling card has been used by its maker the same date will not always be used in connection with it again. The card may then have the date portion cut or torn off (a perforated tearing line being provided as shown in Fig. 1). Preferably, however, separate date cards are used, each of which might, for example, correspond exactly with the portion on the left of the dotted line in Fig. 1 except of course for the different dates perforated in the different cards. A new one of these perforated for the day is put into the machine each morning, and all the items of the day are similarly dated. This saves a large amount of labor which would otherwise be spent in separately dating each card. A series of date cards may be kept on hand for use whenever a special date is desired. In the case of using cards without a punched date column the date should preferably be printed thereon.

Or the date printing mechanism of the machine may be arranged for manual setting without the necessity of using a controlling card, since such setting ordinarily is to be effected but once a day. Such a mechanism might correspond for example to the ordinary and well known dating stamps used in most offices.

The card shown in Fig. 4 consists of a portion 327 which corresponds substantially to the controlling card of Fig. 1 except for the omission of certain printed items, and a portion 328 which corresponds to an ordinary journal entry; the two parts being preferably united by a perforated line so that they may be readily separated. The perforated card alone will be used in the machine of the present invention. But the printing of the journal card and the ledger or perforated card together facilitates the

understanding of the item by persons who are not familiar with the new system.

Fig. 5 shows a ledger card suitable for banks and which contains the columns J, F, K and L of Fig. 2, and, instead of the alphabet columns of the latter, contains columns indicating the amounts deposited and withdrawn. Various simple modifications of the mechanism previously described may be designed to make a record according to this figure.

Fig. 6 shows an even simpler form of bank ledger which may be produced by omitting or suppressing the balance columns of the machine. Any known or suitable feeding mechanism may be used with this and with other recording sheets which have no perforated balance column.

Fig. 7 shows a page of the ledger of the bank bookkeeper containing in addition to the items of Fig. 6 simply a column containing the numbers of the depositors making the several deposits and withdrawals. The provision of additional mechanism for recording the depositor's number is very simple, the mechanism being substantially the same as that previously described for recording dates or amounts.

Fig. 8 shows the bank cashier's book, showing simply the date, depositor, and amount, which items can be taken off a controlling card by the very simplest style of recording mechanism.

Fig. 9 shows a similar ledger, the deposit clerk's. The date, depositor, and the amount of deposit are indicated.

For business in which a meter is used, such as gas, electric, or water companies, for example, the present system of keeping accounts can be very much simplified. The controlling card may be taken direct from the meter and punched to indicate any desired items. A ledger may be kept with such a card, which shows in print only the continuous balance of the customer. For example, Fig. 10 shows a sheet in which the date, the number of cubic feet which the meter reads, the amount corresponding to said number of feet, and the balance standing against the customer's account, are all indicated in perforations, the balance being repeated in print in the last column. Since the balances in this class of accounts seldom or never run higher than four figures, it is possible to arrange all the perforations of the balance on a single horizontal line, taking four spaces on said line for each figure.

Another style of ledger for meter business is indicated in Fig. 47 containing besides the items shown in Fig. 10 two columns for the date of meter reading and the quantity indicated on the meter. This sheet contains so many columns that in order to reduce it to a suitable width the four spaces

for the perforations for each decimal place are arranged in a vertical line. Each horizontal line of the sheet therefore is of double width as compared with the sheet of Fig. 10 5 and as is indicated by the feeding perforations at the sides. This style of ledger has a particular advantage in that the customer's bill may be taken directly off the ledger by a machine similar to that previously described. Fig. 48 is a key to Fig. 47, showing in figures the numbers represented by the perforations of Fig. 47. It will be observed from Fig. 48 that on the date of payment the entry in the ledger repeated the 10 date of the last reading and the quantity of the last reading of the meter, and left blank the gas consumed and the balance columns. With a ledger sheet kept in this way the last 15 two lines and in fact the portion of said two lines within the dotted line 329 will give all the figures necessary for the gas bill of Fig. 49; the latter having the appropriate headings and price per thousand printed thereon beforehand. It will be only 20 necessary therefore to design the machine to take off the dates and quantities of the last two readings, the gas consumed and the amount of the last reading, and the balances 25 of the last two readings, and to print them 30 upon correspondingly located parts of a bill-head.

Modifications of mechanism.—The mechanism for making the recording sheet of Fig. 47 is illustrated in Figs. 50, 51, 52, 53 and 35 53^a, at least in so far as it differs from that previously described. Fig. 51 indicates the arrangement of the perforations in the four vertical spaces to indicate the several integers, and shows that an overlapping system 40 is used similar to that previously described, so that the punch-carrying sector must move up two steps in shifting from any number to the next. This difference necessitates certain modifications of the punching mechanism.

The recording mechanism for ordinary entries from the meter card does not differ in principle from the mechanisms hereinabove described. Special mechanism must 45 be provided however for insuring the repetition of the date and quantity of the meter reading whenever a payment card is put in the machine in place of the usual meter cards (as in the third item in Fig. 48). This 50 payment card will be punched to record the date of payment and the amount of payment, but will not contain any other perforations except a special perforation at the bottom distinguishing a payment card from a meter card. Fig. 50 shows a supplementary pin 355 below the regular controlling pins 24 in position to enter the perforation which indicates that the card is a payment 55 card when the latter is inserted in the pocket Q. The arms 44 which control the

record in the date of meter reading and quantity of meter reading columns are subject to two alternative controls; first, that of the balance 24 when the record is being taken from an ordinary meter card, and, 70 second, that of supplementary pins 356, 357, 358 and 359 at the back of the machine, when the previous record is to be repeated, that is to say, in the use of a payment card. The entry of the forward pin 355 into a 75 perforation in the card or its failure to find such a perforation determines whether one or the other control shall be applied to the arm 44. This arm 44 is controlled by a stop-arm 46 yieldingly connected to an arm 48 and carried upon a supporting arm 43; and the movements of these parts are controlled by the forward movement of slides 360, 361, 362 and 363 corresponding respectively to the pins 356, 357, 358 and 359 at the rear and 80 actuated by said pins, these slides moving either singly or in groups; all as described in connection with the previous mechanism. Each of the slides 360, etc., is connected both to a controlling pin 24 and to one of the 85 feeler pins 356, etc., at the rear. This connection is best shown in the perspective view Fig. 53^a. Each pin 24 is connected by a rear rod or extension 364 and by a pin and slot connection to the corresponding slide, as 360, 90 95 the pin 365 being normally in the forward end of the slide 366 by reason of the backward pull of springs 367 upon the members 360 etc.

The pins 356, etc., are connected by means 100 of levers 368, links 369, and levers 370 to the slides 360 etc., said levers 370 having pins 371 normally in the forward end of slots 372 in the slides. Consequently when any one of the pins 356, etc., is allowed to enter 105 a perforation in the previous line of the recording sheet (these pins being pressed forward continuously by springs 371) it will push forward the corresponding slide 360 at the front of the machine.

This however cannot take place unless the payment-card pin 355 advances, thereby swinging the angle lever 372 so as to carry its end upward out of engagement with the projections 373 on the arms 370. At the 110 same time that this release of the arms 370 occurs there is preferably a locking of the extensions 364 of the ordinary controlling pins 24 by means of a comb 374 whose slots normally stand in register with pins 355 115 carried by said extensions 364 and which slots are raised out of register by the movement of the angle lever 372 so as to prevent forward movement of said extensions 364.

The working of the combinations as heretofore described calls in some cases for a partial movement of one of the slides alone and a continued movement of a second slide with the first one. This is effected when the normal meter card is in use by means of up- 125 130

ward projections 376 upon some of the slides and lateral pins 377 upon other slides. Where, however, the record is to be transmitted from the pins 356, etc., it is preferable that the limitation of relative movements should take place close to said pins, and for this purpose the levers 368 are provided with stops or engaging portions for limiting their relative movements and for effecting the desired groupings. The arrangement is shown in Fig. 56, projections 378 of suitable length and of suitable lateral extension determining the possible movements between the pins.

15

Billing mechanism.

For the purpose of making out bills special attachments may be made to the machine hereinabove described, as indicated in Figs. 20 54 to 56^a, in connection with Figs. 61 and 62. The supports 310 which carry the regular racks 292 for actuating the adding wheels 286 and 287 carry also on their opposite faces racks 379 which are held in place by 25 pin and slot connections permitting a sliding movement for carrying purposes. What we may call dummy adding wheels or billing wheels 380 (so-called in distinction from the regular tabulating or debit and credit adding wheels 286 and 287) are mounted in arms 381 on a shaft 382 which is oscillated to raise the billing wheels out of engagement with the racks 379, or to lower them into engagement with said racks at the appropriate 30 time.

Supposing a department store account to be in question, for example, and it is desired to make the bill of a particular customer, all the sales cards for this particular customer 40 are run through the machine, and with each card the billing wheels are operated to add the several amounts so as to register the total. The card, for example, may be similar to that shown in Fig. 29 which records 45 the customer's number, the goods, and the amount, as well as the date (using of course any desired system of perforations). The bill-head is used as a recording sheet and records in succession the several items. If the 50 customer has made a payment a special card known as a payment card and having a special perforation by which the machine can identify it, is placed in the controlling card pocket Q. The operation of the machine 55 will then not only record the desired information but will subtract from the billing wheels the amount indicated by the payment card, leaving the billing wheels still registering the net total. If it be desired to 60 take off or record sub-totals from the billing wheels this may be done without losing the register of the continuous total in the billing wheels. If it is desired to take a grand total and to leave the billing wheels at zero for a

new bill of another customer, this may also 65 be done. These sub-totaling and grand totaling operations are also controlled by cards suitably perforated.

In the adding operation the billing wheels are held out of engagement with their racks 70 until the completion of the forward movements of these racks, which correspond with the lifting movements of the printing or punching sectors; and are dropped into engagement with their racks so as to be rotated 75 on the backward movement of the racks to their zero position. In a subtracting operation the adding wheels are rotated backward by dropping them into engagement with the racks on the forward movement of 80 the latter, and by lifting them out of engagement before the rearward movement of the racks commences.

The carrying operation from one decimal place to another is effected in a manner 85 similar to that of the regular adding wheels. In adding, the carrying operation involves the addition of 1 to the next higher decimal place. In subtracting, the carrying operation involves the subtracting of 1 from the 90 next higher decimal place. The racks 379 therefore are arranged to move one step forward or backward according as there is an adding or a subtracting operation being performed. The comparatively strong spring 95 383 tends to pull the rack 379 to the right and to add one step in the rotation of the corresponding billing wheel 380; and the rack 379 is released to permit this additional step whenever the adding wheel of the next 100 lower decimal place passes from 9 to 0. Normally, however, the rack is held by a transverse portion of the slot 384 in which is a pin 385 carried upon an arm 386 between the rack and its support and which is 105 pivoted at 387 and held up by a spring 388. The arm 386 is depressed at the proper moment by means of a roller 389 on the end of an arm 390 which is pivoted on the shaft 382 and which carries a lateral connection 110 391 to another arm 392 pivoted on said shaft and which is provided with a projection 393 over which rides a carrying pin 394 of the billing wheel whenever the latter passes from 9 to 0 (in adding; or from 0 to 9 in 115 subtracting). These parts are lapped over each other, and the lateral connections 391 are staggered as indicated by the dotted line arrows in Fig. 55 and the perspective view, Fig. 55^a. Therefore it will be seen that 120 whenever the billing wheel passes zero the arm 386 of the next higher decimal place is depressed and releases its rack 379 which moves forward one extra step.

In a subtracting operation, starting from 125 the same position, that shown in Fig. 54, the rack 379 must move backward one step in carrying. This is effected by means of a

spring 394 pulling the rack in the opposite direction from the spring 383, but which is normally weaker than the spring 383. The outer end of said spring 394 is connected to a slide 395 slidably supported at its upper and lower ends and having teeth 396 and 397 on its under side in the former of which engages a pin 398 carried on the end of an arm 399 on a shaft 400 which turns to the right (by mechanism on the outside of the apparatus hereinafter described) when there is an adding operation, and to the left when there is a subtracting operation. The movement to the right has no effect. The movement to the left shifts the slide 395 to put a tension on the spring 394 greater than that on the spring 383, so that when the rack is released by the passage of the billing wheel of the next lower decimal place from 0 to 9 it will move to the left and cause its billing wheel to register one less than would otherwise be the case. In moving the slide 395 to the left the pin 398 moves so far as to finally escape the tooth 396. In the meantime however the tooth 397 has been caught and held by a fixed pin 397^a from which it is only released by the returning movement of the pin 398 striking up the slide 395. In taking totals off the billing wheels the subtracting movement,—that is to say, the movement of the racks 379 to the left,—is utilized. The billing wheels 394 are dropped into engagement with the racks, and the latter are freed so as to turn to the left under the impulses of their several springs. If each rack moves until its billing wheel is turned back to zero, the type-carrying sectors will be in position to record the total which was registered in the billing wheels. To secure this result therefore it is only necessary to stop the billing wheels when they arrive at zero. This is done by locking the arms 392 which are ordinarily tripped on the passage of the billing wheels from 0 to 9. For this purpose the arms 392 are provided with approximately vertical arms 401 the upper ends of which are adapted to be locked by means of a rod 402 carried at the ends of arms 403 on a shaft 404 operated from the outside of the machine at the proper time.

In Fig. 56 the shaft 404 which controls the locking of the carrying mechanism and is utilized in the totaling operations, the shaft 382 which determines the lifting and lowering of the billing wheels, and the shaft 400 which determines the adding or subtracting operation; are indicated as passing through the principal frame *j* and controlled by mechanism on the outside of said frame.

Fig. 56^a is a section approximately on the line 56^a of Fig. 56 looking in the direction of the arrow, and shows the positions of the

three pins 405, 406 and 407 which determine the three operations above referred to. The subtracting operation alone would be performed whenever there is a payment card, and this card will have a single perforation therein registering with the pin 405. If the grand total is to be taken, the card will be provided with perforations corresponding to both 405 and 406. If a sub-total is to be taken, the card will have perforations corresponding to the three pins 405, 406 and 407.

The turning of the adding or subtracting shaft 400 to the right or to the left is effected by means of an arm 408 fixed thereon and which is adapted to be brought back to the intermediate vertical position by means of pins or rollers 409 adapted to engage the upper and the lower portions of said arm and carried upon a slide 410 which is positively thrown to the rear at each operation of the machine by means of an arm 411 on the shaft 34 which is actuated at the beginning of each operation of the machine as previously described. The arm 411 throws the slide 410 to the rear by engaging a pin 412, and the slide is held in place by a spring pawl 413 engaging a pin 414. At the end of the return movement the arm 411 strikes a projection 415 of the pawl and throws it out of engagement with the slide 410, and the spring 416 returns the slide and restores the shaft 400 to its intermediate position. The shaft 382 which carries the billing wheels is provided with an arm 417, and with another depending arm 100 carrying a pin 418. The pin 418 lies in a slot in the arm 411, so that the billing wheels cannot drop into operation except after the first movement of the arm 411. The arm 417 is locked by a pawl 419 which we may call the adding pawl, since it normally holds the wheels up out of engagement with their racks until the end of the recording movement of the machine and only allows them to drop into engagement before the return movement of the sectors and racks. For this purpose the pawl 419 is connected by a link 420 with an arm 421 which is loose on the shaft 294 and which is moved to the left by engagement with the pin 295^a, in a manner similar to the arm 295 of Fig. 14. It is at the end of the forward stroke of the racks, and after they have passed the billing wheels, that this operation takes place, so that they are dropped into engagement and are rotated on the return movement of the racks, thus performing the regular operation of addition without the aid of any special perforations in the card.

The arm 421 is connected by a spring 422 with the arm 295 which is fixed on the shaft 294. Unless the arm 295 is restrained as

hereinafter described the movement of the arm 421 effects a corresponding movement of the arm 295. The spring 296 in this case is connected to the arm 421 for retracting it 5 and the arm 295.

When a subtracting operation is to be effected the first controlling pin 405 moves forward and carries with it the link 423 which actuates an arm 424 loose on the shaft 10 303 and which is connected at its lower end to a link 424 which is connected by a pin and slot to the upper end of the arm 408 on the subtracting shaft 400; which shaft is thereby turned to set the carrying mechanism for 15 subtraction. The slide 410 is of course withdrawn to release the arm 408 previous to or simultaneously with the operation of the link 424. The pin 418 is released at the same time, and so is the adding pawl 419 by reason 20 of the connection of the latter through the link 420 to the arm 424. This release takes place upon the forward movement of the plate 26 which is prior to any movement of the racks which operate the billing wheels. 25 Therefore on the advance or forward movement of these racks they find the billing wheels already dropped into engagement, and they turn the billing wheels in the direction to subtract. After the forward 30 movement of the racks the billing wheels must be left out of engagement so that the rearward return movement of the racks shall be without effect; (otherwise this movement would add to the wheels what had 35 just been subtracted from them). The lifting movement is effected through an arm 425 on the shaft 382 which carries the supporting frame of the wheels. The arm 425 has at its end a pin 426 adapted to be engaged 40 by a shoulder on the under side of a slide 427 the opposite end of which is connected with an arm 428 on the shaft of the regular adding wheels, and which after the sectors are set and during the punching movement 45 is rocked to the right by means of the arm 322, as illustrated in Fig. 14. When the shaft 382 is rocked by this means, the arm 417 moves up to such an extent as to be caught and held by the supplementary pawl 50 438 until the end of that operation when the pawl is pressed backward by the roller indicated on the end of the arm 33.

In order to record a grand total from the billing wheels, both the pins 405 and 406 55 move forward. The effect of the movement of the pin 405 is the same as just described for subtracting. That is, on the forward movement of the racks they actuate the wheels; but with this exception,—that the 60 carrying devices are locked so that the wheels stop at zero. As in simple subtracting, there is no actuation of the wheels on the return movement of the racks; consequently the billing wheels stand at zero after the operation 65 and an entirely new total begins. The

locking of the carrying devices to prevent the wheels moving beyond the zero point as previously explained is effected by turning the shaft 404 to the left. This shaft carries on the inner side of the plate or frame *j* an arm 429 which is connected by a link 430 to a second link 431 which is moved forward when the second pin 406 finds a hole in the card. In the simple subtracting operation the result shows upon the regular adding wheels of the machine as well as upon the billing wheels. In the taking off of totals from the billing wheels however there should be no operation of the regular adding wheels. To prevent this the arm 295 is engaged by a hook 432 carried on a short shaft having an arm 433 connected to the point of articulation of the links 430 and 431. The hook 432 is thrown up at the beginning of the operation and thus holds both the regular 85 adding wheels out of commission.

When a sub-total is to be recorded the present totaling of the adding wheels is recorded in the same manner as above described for a grand total; and after the forward movement of the racks the adding wheels are allowed to remain in gear therewith, so that on the return movement of the racks the adding wheels will be restored to the positions which they occupied before the 90 taking off of the sub-total. In this case the three pins 405, 406 and 407 will find suitable openings in the card, and when they are advanced they will effect through the links 423 and 431 the same operations as in taking off 100 a grand total. In addition the rod 434 will be thrust backward. The rear end of this rod engages an arm on a short shaft 435 which shaft carries a second arm 436 which has a pin 437 traveling in a slot in the sliding pawl 438 by which the wheels are lifted out of engagement at the end of the forward stroke of the racks. The thrust on the rod 105 134 causes an upward movement of the arm 436 and the pin 437, and lifts the pawl 427 114 out of line with the pin 426, so that when at the end of the advance movement of the racks the pawl 427 is thrust to the rear it will no longer have any effect upon the wheels, and the wheels will be lifted in gear 115 with the racks so as to be returned to their starting position upon the return of the racks.

The pins 405, 406 and 407 are similar to the regular controlling pins 24, being provided with springs which are compressed on the forward movement of the plate 26. If the cards are to be fed by hand to the machine and not removed until the complete return of the handle of the machine to its 120 starting point, the pins may be connected rigidly to the links 423, and 431 and the rod 434. The machine may be adapted however for feeding the controlling cards thereto by machinery, and I have designed such 125

machines in which the controlling card is removed from the pocket and a new one substituted during the return movement of the main handle of the apparatus. With 5 such an automatic feed it is necessary to interpose motion-transmitting devices between the pins and the mechanism controlled by them, whereby the pins may be withdrawn without at the same time withdrawing 10 the controlled mechanism. This result is accomplished by the mechanism illustrated. The links 423 and 431 are connected respectively to arms 439 and 440 rocked about their lower ends, and the 15 thrust rod 434 is connected to a downward extension of a similar arm 441. These arms are drawn back by springs 442, and are provided each with a stopping device which is illustrated only in connection with the arm 20 441. This stopping device comprises a pin 443 upon which rests an arm 444 on a shaft 445 which carries also an angle lever 446 having a lifting rod 447 underlying the several arms 444. The angle lever 446 is connected 25 by a link 448 with any part of the apparatus which moves to the rear during the advance movement of the apparatus, and forward again at the end of such advance movement. Such a part of the mechanism 30 for example is the lower arm of the lever 31, Fig. 14. The arms 444 are therefore freed during the advance movement of the apparatus by the downward movement of the rod 447. When any one of the arms 35 439, 440 and 441 moves forward, its stop-arm 444 moves down in line with the pin 443 and prevents the rearward movement of the arm even though the corresponding controlling pin shall be withdrawn out of 40 the pocket. The pins 405, 406 and 407 merely pass loosely through the upper ends of the arms 439, 440 and 441, exerting a positive forward action by means of the enlargements 449 of the pins, but moving 45 backward freely without affecting the arms.

The billing and subtracting mechanisms above described are improvements upon certain billing and subtracting mechanisms described by me in a previous application No. 50 331,757, of August 23, 1906.

New balance mechanism.—After taking off the grand total from the billing mechanism the amount will ordinarily be lost,—that is, canceled out of the machine. It is 55 desirable to keep a record of this, and I propose to make a new balance card simultaneously with the entering of the grand total on the bill (or at least before losing this grand total out of the machine). Such a card, for example, is illustrated in Fig. 61, and shows the customer's number in perforations and in print, (the first two columns), any additional information, as the date, "by balance," etc., (in the third column), and 60 65 the customer's balance (in the last column).

The adapting of the machine to make this card calls only for a small additional recording pocket at the rear of the machine alongside of the regular recording sheet pocket, and for mechanism similar to that shown 70 in Figs. 43, 44 and 45 for transferring the movements of the regular printing or punching sectors laterally to corresponding sectors in line with the new balance card. The perspective view, Fig. 62, illustrates the arrangement of the pockets; from which the locations of the parts of the mechanism will be understood.

The frame of the machine as a whole is indicated at 446. The controlling card 80 pocket Q and the recording sheet pocket R are arranged at the left with the bill-head 467 extending up out of the latter, and the supplementary pocket 468 carrying the new balance card 469 is at the right 85 immediately alongside the recording sheet pocket R.

Reciprocating mechanism.

In place of the various type- and punch-carrying sectors above referred to, and which operate with oscillating movements about the center, there may be substituted rectilinearly moving parts on the principle illustrated in Figs. 28 and 30. These mechanisms are designed for printing the letters of the alphabet only (Fig. 28) or the letters of the alphabet and also the Arabic numerals (Fig. 30). The card by which these mechanisms are actuated is indicated in 90 Fig. 29. The lower two squares of each column under the section "goods" indicate whether the letter represented is in the first, second or third division. If both the squares are punched, a letter in the third division is 95 indicated. If only the next to the lowest square is punched, a letter in the second division; and if neither of the two supplementary squares is punched, the first division. The proper one of the three divisions 100 of the alphabet being indicated, the successive squares above the supplementary ones correspond to the successive letters A, B, C, etc., J, K, L, etc., or S, T, U, etc. According to this system it will be observed that the 105 card reads "black silk."

The type-carriers 450 carry at their heads the several types 451 which are first brought into register by lifting the carriers 450 and are then struck by a hammer 452 to effect 120 the printing. Each carrier is lifted by a coiled spring 453. The control-rods 454 are connected with the controlling pins which enter the card pocket and move forward as said pins move forward. The first nine control-rods are alike. If any one of these rods moves forward and its head 455 moves forward to limit the upward movement of the type-carrier, the latter will move up to a position corresponding to that rod for 125 130

either the first, second, or other division of the system of characters used. For moving through the first division of the alphabet a stop 456 is provided which engages the head of the operated control-rod 454; for moving through the letters of the second division a second stop 457 is provided; and for moving through the letters of the third division a third stop 458. The part 459 serves as a stop engaging the part 460 of the frame of the machine, and the hammer 452 is arranged above the uppermost type so that when no one of the control-rods is operated and the type carrier does not rise, the hammer will not print anything on the sheet. The supplementary control rods 461, 462 do not pass beyond the type carrier, but are supported at their rear ends in guides 463. The rod 461 is connected to the stop 456, the latter being pivoted at its lower end. The rod 462 has a depending arm 464 which engages the stop 457 which is also pivoted at its lower end. When neither one of the supplementary rods finds a perforation in the card, the stop 456 is operative, and the type carrier will move only through the letters of the first division, stopping at the letter corresponding to the main rod 454 which is operated. When the stop 456 is pulled forward out of its operative position, the type carrier will rise until the stop 457 engages the rod 454 which has been operated, and the machine will print one of the letters of the second division. Similarly when both the stops 456 and 457 are pulled forward to their inoperative positions, the carrier will move upward until the stop 458 engages the operated control rod 454, and the machine will print one of the letters of the third division. Accordingly when neither one of the supplementary rods operates, the letters of the first division are printed; when the rod 461 operates, the letters of the second division are printed; and when the rod 462 operates, the letters of the third division are printed. The movable stops 456 and 457 are held impositively, in either position to which they are shifted, by latches 465.

Instead of arranging this alphabet mechanism so that both the rods 461 and 462 must be operated when the lowermost shoulder 457 is to come into play, it may be arranged so that the rod 462 alone shall operate both of the movable shoulders 456 and 457. This would be preferable in calling for only a single perforation of the card for the purpose of indicating in which division of the alphabet the letter to be printed is found.

This so-called "alphabet" mechanism may be used for any system of characters, its special advantage being to make possible the use of a number of characters in excess of the number of spaces in each column of the card which is to control the printing. Even

the ten Arabic numerals, for example, might be subdivided so as to permit the use of a card with a smaller number of squares in each column.

Or, as in Fig. 30, each carrier may be provided with both numerals and letters of the alphabet, so that either a figure or a letter may be printed at will. In this case there will be four groups of characters, each group containing nine characters, the first group or division running from 1 to 9, the second running from zero, A, B, etc., through H, the third running from I through Q, and the fourth running from R through Z. Since there are four groups, there will be three movable shoulders, 456, 457, and 457^a, and a fixed shoulder 458, and there will be three controlling rods 461, 462, and 462^a, the system being a simple extension of that shown in Fig. 28.

This mechanism is more fully described in my previous application No. 387,868, of August 9, 1907, and is similar in principle to the alphabet mechanism shown in my earlier application of August 23, 1906, previously referred to.

The casing and other outside parts of the machine may be of any usual or suitable type, being largely a matter of taste and of the appearance desired. The principal mechanism hereinabove explained is designed to go into a case of approximately the shape of a Burroughs adding machine casing, but with a controlling card pocket at the front and omitting the adding machine keys on the top.

Though I have described with great particularity of detail certain specific embodiments of the invention, yet it is not to be understood therefrom that the invention is restricted to the particular elements, combinations, systems and methods described. Various modifications thereof may be made in detail, in the order of operations, and in the arrangements and combinations described without departure from the invention.

Definitions.—In the claims hereinafter the following words or terms are generally used with the following meanings, though it will be understood that these meanings are not exclusive of other possible meanings and are not invariable. The word "perforations" includes various equivalent physical differences, such for example as protuberances, depressions, slots, weakened parts, and other differences in shape. The word "recording" refers either to printing, perforating, or other method of making a record; while the word "registering" is used to indicate the moving of the mechanism to a desired position either with or without the making of a record; and by "printing" I refer to the making of printed or written characters by any suitable means. "Listing" is a kind of

recording which includes not merely amounts, dates, or other numbers, but also names or other alphabetical designations. "Amount-printing mechanism" refers to 5 mechanism for printing numerals alone, such as dates, journal numbers, amounts, or the like. The "reversing" of a record is the changing of its character, as from black to red, from debit to credit, etc. The term 10 "entry" is used to include all matters recorded to indicate one transaction, while the term "item" is used to indicate a separate part of a complete record or entry. The taking of a "grand total" (where used 15 in contradistinction to a sub-total) refers to the operation in which the registering portions of the machine are turned to zero, while a "sub-total" refers to an operation in which the mechanism is returned to a position 20 to register the same amount as before. The "carriers" referred to may be pivoted sectors or arms, or may be otherwise shaped and moved, and the term "arm" is used to include a swinging member or 25 any equivalent sliding or similarly moving element. The term "punching plate" includes not only the particular selecting and actuating plates illustrated, but any punch operator or a selector such for example as a 30 plate which permits different combinations of punches to pass instead of forcing such combinations forward. By "a machine of the class described" I mean to include not only the entire machine with the various 35 attachments and modifications described, but also the various unitary parts or sub-combinations of mechanism described.

I do not in the present application claim the controlling cards and recording sheets 40 and the methods described, nor the means for punching and feeding the recording sheet, but I am not to be understood as thereby waiving my right to claim the same in separate applications.

45 What I claim is:—

1. A machine of the class described including amount printing mechanism, amount reversing mechanism for reversing the printing of such amounts as debits and credits respectively, and amount reversing 50 punches controlling said reversing mechanism.

2. A machine of the class described including balance punching mechanism adapted 55 to record by perforations the balances of a series of debits and credits and balance printing mechanism operatively connected to said balance punching mechanism so as to record in print the balance which is 60 recorded by perforations on the same operation of the machine.

3. A machine of the class described including mechanism for adding or subtracting a reading on a controlling card to or 65 from a previous reading on a recording

sheet and automatically reproducing the reading from the controlling card in one color or another according to perforations in the controlling card.

4. A machine of the class described including mechanism for adding or subtracting a reading on a controlling card to or 70 from a previous reading on a recording sheet and automatically reproducing the reading from the controlling card in one color or another according to perforations 75 in the recording sheet.

5. A machine of the class described including mechanism for adding or subtracting a reading on a controlling card to or 80 from a previous reading on a recording sheet and automatically reproducing the reading from the controlling card in one color or another according to perforations 85 in the controlling card and in the recording sheet.

6. A machine of the class described including mechanism for automatically recording respectively as debits and as credits amounts indicated on cards introduced 90 successively into the machine.

7. A machine of the class described including pivoted sectors whose movements determine a number of items, and means for recording said items by perforations corresponding to the respective items. 95

8. A machine of the class described including mechanism for determining by means of a single controlling card a plurality of letters or numerals and mechanism 100 for recording them all at one operation.

9. A machine of the class described including mechanism controlled by a card for making a record on a recording sheet and means for preventing the operation of said 105 mechanism when either the controlling card or the recording sheet is not in place.

10. A machine of the class described adapted to be controlled by a card and including mechanisms for recording an item 110 on a controlling card and a preceding item on a recording sheet respectively.

11. A machine of the class described including mechanism for recording an item on a card and a preceding item on a recording sheet respectively, and means controlled by said card for determining which 115 of these mechanisms shall operate.

12. A machine of the class described including mechanism for recording items under control of a perforated card and adapted to be used also as an addressing machine. 120

13. A machine of the class described including billing wheels which add or subtract the amount on the controlling card 125 and having means controlled by said card for determining whether to add or subtract.

14. A machine of the class described adapted to be controlled by a perforated card and having a dummy set of adding 130

- wheels which adds and subtracts, and additional wheels for tabulating items.
15. A machine of the class described adapted to be controlled by a perforated card and having means for recording a plurality of items and means for automatically selecting and causing the recording of said items alternatively. 70
16. A machine of the class described including means for recording three items and means controlled by a controlling card and by the recording sheet for selecting and causing the recording of one or another of said items. 75
- 15 17. A machine of the class described including sectors and operating mechanism therefor adapted to be controlled by a perforated card, each sector and its operating mechanism being within the width of a single column of the recording sheet. 80
18. In a machine of the class described the combination with a pair of sectors of means for determining the movement of one of said sectors, and a movable Y-piece for determining the movement of the second sector relatively to the first, whereby a combination of movements may be converted into a single motion equal to the total of the two movements above referred to. 90
- 30 19. In a machine of the class described a ribbon, adding wheels, a perforating pin and a debit and credit mechanism adapted to set said ribbon, adding wheels, and perforating pin in one short continuous movement. 95
- 35 20. In a machine of the class described, recording mechanism, a controlling pin controlling said mechanism and adapted to enter perforations in the recording sheet, and means for insuring the entrance of said controlling pin at the beginning of the operation, as soon as the recording sheet is properly placed. 100
- 40 21. In a machine of the class described type carriers carrying the entire alphabet on one carrier, and means controllable by a perforated card for determining the movement of said carriers. 105
- 45 22. In a machine of the class described type carriers carrying the entire alphabet and the Arabic digits on one carrier, and means controllable by a perforated card for determining the movement of said carriers. 110
- 50 23. In a machine of the class described perforated-card controlled means for algebraically adding two numbers, automatically adding when they are both positive or both negative and automatically subtracting when one is positive and another negative. 115
- 55 24. A machine of the class described including perforated-card controlled means for algebraically adding plus and minus quantities to another quantity by automatically determining when the quantity to be added is a minus quantity and adding the complement of said minus quantity. 120
- 60 25. A machine of the class described including perforated-card controlled means for algebraically adding plus and minus quantities to another quantity by automatically determining when the quantity to be added is a minus quantity and adding the complement of said minus quantity, and means for recording the sum as a positive amount if said other quantity be positive and greater than said minus quantity. 125
- 65 26. A machine of the class described including perforated-card controlled means for algebraically adding a minus quantity to another quantity by adding the complement of said minus quantity, and means for determining the complement of the result if said other quantity be positive and less than said minus quantity. 130
27. A machine of the class described including perforated-card controlled means for algebraically adding a minus quantity to another quantity by adding the complement of said minus quantity, means for determining the complement of the result if said other quantity be positive and less than said minus quantity, and means for recording such complement of the result as a negative quantity. 135
28. A machine of the class described including means for algebraically adding two numbers, means for punching the recording sheet when the sum is a negative quantity, and means for printing such sum as a negative quantity. 140
29. In a machine of the class described two elements whose movements correspond respectively to two numbers, a carrier whose position determines the manner of punching a sheet to indicate the algebraic sum of said two numbers, and means for moving said carrier a distance corresponding to the sum of the movements of said two elements. 145
30. In a machine of the class described two elements whose movements correspond respectively to two numbers, a carrier whose position determines the manner of punching a sheet to indicate the algebraic sum of said two numbers, means for moving said carrier a distance corresponding to the sum of the movements of said two elements and means for "carrying" from one decimal place to the next higher. 150
31. In a machine of the class described two elements whose movements correspond respectively to two numbers, a carrier whose position determines the manner of punching a sheet to indicate the algebraic sum of said two numbers, means for moving said carrier a distance corresponding to the sum of the movements of said two elements and means for moving said carrier further to a position corresponding with the arithmetical difference between said two numbers when one of them is a minus quantity. 155
32. In a machine of the class described 160

two elements whose movements correspond respectively to two numbers, a carrier whose position determines the manner of punching a sheet to indicate the algebraic sum of said 5 two numbers, means for moving said carrier a distance corresponding to the sum of the movements of said two elements, means for moving said carrier further to a position corresponding with the arithmetical difference between said two numbers when the smaller one of them is a minus quantity, and means for recording such difference as a positive quantity.

33. In a machine of the class described 15 two elements whose movements correspond respectively to two numbers, a carrier whose position determines the manner of punching a sheet to indicate the algebraic sum of said two numbers, means for moving said carrier a distance corresponding to the sum of the movements of said two elements, means for moving said carrier further to a position corresponding with the arithmetical difference between said two numbers when 20 the larger one of them is a minus quantity, and means for recording such difference as a negative quantity.

34. In a machine of the class described 30 two elements whose movements correspond respectively to two numbers, a carrier whose position determines the manner of punching a sheet to indicate the algebraic sum of said two numbers, means for moving said carrier a distance corresponding to the sum of the movements of said two elements, means for moving said carrier further to a position corresponding with the arithmetical difference between said two numbers when the larger one of them is a minus quantity, and 35 means for punching the recording sheet to indicate that such difference is a negative quantity.

35. In a machine of the class described two elements whose movements correspond 5 respectively to two numbers, a carrier whose position determines the manner of punching a sheet to indicate the algebraic sum of said two numbers, means for moving said carrier a distance corresponding to the sum of the movements of said two elements, means for moving said carrier further to a position corresponding with the arithmetical difference between said two numbers when the larger one of them is a minus quantity, and means for punching the recording sheet to indicate that such difference is a negative quantity, and means for printing such difference as a negative quantity.

36. In a machine of the class described two elements whose movements correspond respectively to two numbers, a carrier whose position determines the manner of punching a sheet to indicate the algebraic sum of said two numbers, means for moving said carrier a distance corresponding to the sum

of the movements of said two elements, said carrier being adapted to move beyond said distance.

37. In a machine of the class described two elements whose movements correspond 70 respectively to two numbers, a carrier whose position determines the manner of punching a sheet to indicate the algebraic sum of said two numbers, means for moving said carrier a distance corresponding to the sum 75 of the movements of said two elements, and means for causing a movement of said carrier beyond said distance when one of said numbers is negative.

38. In a machine of the class described 80 two elements whose movements correspond respectively to two numbers, a carrier whose position determines the manner of punching a sheet to indicate the algebraic sum of said two numbers, means for moving said carrier a distance corresponding to the sum of the movements of said two elements, said carrier being adapted to move beyond said distance, and stopping means normally inoperative and determining the limit of movement of said carrier beyond said distance.

39. In a machine of the class described two elements whose movements correspond 85 respectively to two numbers, a carrier whose position determines the manner of punching a sheet to indicate the algebraic sum of said two numbers, means for moving said carrier a distance corresponding to the sum of the movements of said two elements, said carrier being adapted to move beyond said 90 distance, a pivoted stop on said carrier adapted to swing past a series of fixed stops carried by said means, and means for determining the movement of said pivoted stop.

40. In a machine of the class described 105 two elements whose movements correspond respectively to two numbers, a carrier whose position determines the manner of punching a sheet to indicate the algebraic sum of said two numbers, means for moving said carrier 110 a distance corresponding to the sum of the movements of said two elements and a punching plate carried by said carrier containing a complete series of punching spaces and a repetition of at least a part of said 115 complete series.

41. In a machine of the class described 120 two elements whose movements correspond respectively to two numbers, a carrier whose position determines the manner of punching a sheet to indicate the algebraic sum of said two numbers, means for moving said carrier a distance corresponding to the sum of the movement of said two elements and a punching plate carried by said carrier 125 containing two complete series of punching spaces and additional punching spaces beyond said two series.

42. In a machine of the class described 130 two elements whose movements correspond

- respectively to two numbers, a carrier whose position determines the manner of punching a sheet to indicate the algebraic sum of said two numbers, means for moving said carrier a distance corresponding to the sum of the movements of said two elements and a punching plate carried by said carrier containing a series of punching spaces consisting of solid and open portions in different arrangements. 5
43. In a machine of the class described two elements whose movements correspond respectively to two numbers, a carrier whose position determines the manner of punching a sheet to indicate the algebraic sum of said two numbers, means for moving said carrier a distance corresponding to the sum of movements of said two elements and a punching plate carried by said carrier containing a series of punching spaces consisting of solid and open portions in different arrangements, said spaces overlapping each other so that the lower part of one coincides with the upper part of the next. 10
44. In a machine of the class described an amount arm moving a distance corresponding to an amount, a previous balance arm moving a distance corresponding to a previous balance, a present balance arm moved by the first two arms a distance corresponding to the sum of their movements, a balance punching plate normally moving with said present balance arm, and connecting means between said plate and said present balance arm for causing said plate to move relatively to said arm. 15
45. In a machine of the class described two elements whose movements correspond respectively to two numbers, a carrier whose position determines the manner of punching a sheet to indicate the algebraic sum of said two numbers, and means for moving said carrier a distance corresponding to the sum of the movements of said two elements, a set of punches, means carried by said carrier for forcing them forward and a comb for retracting them and adapted to be removed therefrom by a lateral movement so as to permit the withdrawal of the punches. 20
46. In a machine of the class described perforating sectors and printing sectors separately constructed and rigidly connected so as to act as one piece of mechanism. 25
47. In a machine of the class described the combination of balance punching and balance printing mechanisms and a common operating means therefor. 30
48. In a machine of the class described balance punching mechanism and amount mechanism, the former adapted to move from one figure to the next by movements of one half the length of those of the amount mechanism. 35
49. In a machine of the class described two elements whose movements correspond respectively to two numbers, a carrier whose position determines the manner of punching a sheet to indicate the algebraic sum of said two numbers, and means for moving said carrier a distance corresponding to the sum of the movements of said two elements, and two movable stops for determining further movements of said carrier. 40
50. In a machine of the class described perforated-card controlled means for automatically determining the signs, as plus or minus, of two numbers and printing the algebraic sum of said numbers, said means including a type carrier whose movement corresponds to such sum. 45
51. In a machine of the class described printing sectors t , corresponding punching sectors, sleeves connecting each printing sector to its corresponding punching sector, and a spring for turning each sleeve and the two sectors carried thereby. 50
52. In a machine of the class described a feeler adapted to enter a perforation in a controlling card and to thereby cause the making of a succeeding perforation therein. 55
53. In a machine of the class described adapted to register an amount as a debit or as a credit under control of a card, feelers each adapted to enter a perforation in said controlling card and to thereby cause the making of a succeeding perforation therein, and means actuated by the entry of succeeding pairs of said feelers for successively reversing the effect of said card as a debit or a credit. 60
54. In a machine of the class described debit and credit mechanism under control of a card and including feelers adapted to enter perforations in said card, and means actuated by the entry of successive pairs of said feelers for successively reversing the effect of said card as a debit or a credit. 65
55. In a machine of the class described debit and credit mechanism under control of a card and including feelers adapted to enter perforations in said card, levers 109 between said feelers, said levers being introduced and omitted alternately between succeeding pairs of said feelers, and mechanism controlled by said levers for reversing the effect of said card as a debit or a credit. 70
56. In a machine of the class described debit and credit mechanism under control of a card and including feelers adapted to enter perforations in said card, levers 109 between said feelers, said levers being introduced and omitted alternately between succeeding pairs of said feelers, and a sector 113 which is provided with a stop and with an opening and which is moved by said levers, the movement of said stop and of said opening to operative position alternately. 75

- determining alternately a debit and a credit record by the machine.
57. In a machine of the class described adapted to record on a recording sheet a distribution or a debtor or a creditor, a sector 119 whose position determines whether the machine shall record a distribution on the one hand or a debtor or creditor on the other hand; mechanism adapted to be controlled by a controlling card for moving said sector from one position to the other, and mechanism adapted to be controlled by said recording sheet for reversing the effect of said controlling card.
- 15 58. In a machine of the class described adapted to record a distribution or a debtor or a creditor, a sector 119 whose position determines whether the machine shall record a distribution on the one hand or a debtor or creditor on the other hand, and means controlled by said sector for causing the record to be made in black or in red, said sector being controllable by a perforated card.
- 20 59. In a machine of the class described adapted to record a distribution or a debtor or a creditor, a sector 119 whose position determines whether the machine shall record a distribution on the one hand or a debtor or creditor on the other hand, and means controlled by said sector for causing the adding of the amount to a previous balance or its subtraction therefrom.
- 25 60. In a machine of the class described adapted to record on a recording sheet a distribution or a debtor or a creditor, a sector 119 whose position determines whether the machine shall record a distribution on the one hand or a debtor or a creditor on the other hand, a sector 122 which by its position causes the adding or subtracting of the amount to or from a previous balance and whose position is controlled by the sector 119, and means controlled by the recording sheet for reversing the effect of the sector 119 on the sector 122.
- 30 61. In a registering machine of the class described mechanism adapted to be controlled by a perforated card and a lock normally operative to prevent a registration, and means for holding it so until a controlling card is introduced.
- 35 62. In a registering machine of the class described adapted to be controlled by a perforated card and a lock normally operative to prevent a registration, a setting pin adapted to enter a setting hole in a controlling card, and means for holding said lock operative except when said pin operates.
- 40 63. In a registering machine of the class described adapted to be controlled by a perforated card and a lock normally operative to prevent a registration, a setting pin adapted to enter a setting hole in a control-
- ling card, means for holding said lock operative except when said pin operates, and means for holding said lock operative except when such card is introduced.
- 45 64. In a machine of the class described a set of recording sectors, a plurality of sets of operating arms each adapted to actuate said sectors, and means controlled jointly by a controlling card and a recording sheet for selecting and causing the operation of only one of said sets of arms.
- 50 65. In a machine of the class described perforated-card controlled mechanism for recording a series of items in a line, and means for automatically recording in a succeeding line a repetition of one or more of the previous items.
- 55 66. In a machine of the class described a billing mechanism including operating racks, billing wheels adapted to be engaged with and disengaged from said racks, carrying mechanism adapted to be locked, a shaft 404 controlling the locking of the carrying mechanism, a shaft 382 determining the engagement or non-engagement of the billing wheels with their operating racks, a shaft 400 which determines whether the operation shall be an addition or a subtraction, controlling pins adapted to enter perforations in a controlling card, and means controlled by said pins for actuating said shafts in accordance with the perforations in the card.
- 60 67. In a machine of the class described an operating shaft, perforated controlling cards, controlling pins adapted to enter the perforations of the cards, recording mechanism controlled by said pins and actuated by said operating shaft, and means for retracting said pins to permit removal of the card before the completion of the movement of said shaft.
- 65 68. In a machine of the class described perforated controlling cards, controlling pins adapted to enter the perforations of the cards, recording mechanism controlled by said pins and intermediate controlling devices set upon the entrance of said pins into such perforations, and means for withdrawing said pins promptly and before the withdrawal of said intermediate controlling devices, to permit mechanical or other rapid feed of the controlling cards.
- 70 69. In a machine of the class described means for holding two recording sheets and mechanism for automatically selecting and repeating on one any desired parts of the record made on the other.
- 75 70. In a machine of the class described means for holding two recording sheets and mechanism for automatically selecting and repeating on one the balance which is recorded on the other.
- 75 71. In a machine of the class described means for making a bill under the control

of controlling cards, means for printing the final balance on said bill, means for punching a card to control in a subsequent operation of the machine the recording of said balance as a "new balance", and a common mechanism for actuating said balance printing and said punching means.

In witness whereof, I have herunto signed my name in the presence of two subscribing witnesses.

JOHN ROYDEN PEIRCE.
